UNITED STATES PATENT OFFICE.

OTTO ASMUSSEN, OF BROOKLYN, NEW YORK.

COMBINED AUTOMATIC BURGLAR AND FIRE ALARM SYSTEM AND TELEPHONE SERVICE.

1,150,239.

Specification of Letters Patent. Patented Aug. 17, 1915.

Application filed November 7, 1914. Serial No. 870,751.

To all whom it may concern:

Be it known that I, Otto AsmusSEN, a subject of the King of Denmark, and a resident of Brooklyn, in the county of Kings and State of New York, have invented a new and useful Combined Automatic Bur- glar and Fire Alarm System and Telephone Service, of which the following is a specifi- cation.

- 10 This invention is a system employing a central station or watch house which is elec- trically connected with a plurality of sub- scribers' stations, there being devices lo- cated at the subscribers' stations, and indi- 15 cating apparatus at the central station whereby a burglar alarm or fire alarm may be automatically sent in to the central station from any one or more of the sub- scribers' stations.
- 20 One of the objects of the invention is to provide a single circuit over which both the burglar and fire alarm signals may be sent from the subscriber's station to the central station.
- 25 A further object of the invention is to provide a system whereby, should several subscribers' stations attempt to signal the central station at the same time, the signals from the various subscribers' stations will 30 be successively received at the central station, and this is accomplished, generally, by providing means at the subscriber's station for repeating the signal indefinitely until the particular subscriber's station is 35 released from the central station, whereupon the next subscriber's station in order has its signal impressed at the central station and when the second station is released, the signal from the third station is received, etc.
- 40 Another object of the invention is to pro- vide local signals at the subscribers' stations which will be set into action as soon as the subscriber's station begins signaling the central station and continue in action as 45 long as the subscriber's station continues to signal the central station, viz.—until the central station operator releases the sub- scriber's station.

A further object of the invention is to 50 provide means whereby the lines and connec- tions through the subscribers' stations may be tested from the central station in order to locate faults in the system, and in this connection, the invention includes 55 means whereby any subscriber's station may

be disconnected from the system without in- terference with the operation of the re- maining stations so that should the appara- tus of a subscriber's station become dam- 60 aged, as when the house burns down, etc., that station can be immediately cut out of the system.

Again it is the object of the invention to provide for telephonic communication be- 65 tween the subscribers' stations and the cen- tral station or between two subscribers' stations, using the same line wires for the tele- phone circuit as for the burglar and fire alarm circuits, and controlling the telephone connection at the central station whereby 70 the central station operator can call any sub- scriber or connect any subscriber with any other subscriber, the connections being so made that only the connected subscribers can converse telephonically, while the other 75 stations are rendered telephonically "dead."

Another object of the invention is to pro- 80 vide a system for the purposes described in which the operating circuits are of the nor- mally closed type, whereby any interrup- tion of the current will be signalized at the central station.

Another object of the invention is to make 85 provision for the breaking of the main line circuits to the central office through the automatic switches of the subscribers' stations in the event that the signal wheels of those stations should stop with the contact brushes on any of the contact plates.

In its generic nature the invention pro- 90 vides a central station in which is located a polarized relay, an audible signal and two distinct visual signals, one for the fire alarm indication and one for the burglar alarm in- 95 dication, the signals being controlled by the polarized relay; a resetting device is also provided and a main line circuit (either metallic or ground return) connects the central station with the subscribers' stations, of which latter there may be any desired 100 number connected in the line circuit, and each subscriber's station includes a single repeating impulsator or telegraphing de- 105 vice by means of which the station's pre- determined identification signal is telegraphed by successive repetitions until received and noted at the central station, and by the central station operator the subscriber's station is released or reset; two distinct sets of 110 switching devices, one for the burglar alarm

and one for the fire alarm, are located at each subscriber's station and coöperative connections are provided between the switching devices and the impulsator and 5 include a source of electrical energy for setting the impulsator into action to send out the impulses of the desired polarity into the main line circuit to actuate the polarized relay at the central station and thereby set 10 the proper signal. Means are also provided under control of the central station operator for resetting the switching device and in turn stopping the action of the signaling device. The apparatus of each station also 15 includes two main switch relays, a set of automatic switches, a set of bridging relays, main line opening relays, and a telephone set, the whole being so coöordinated that by means of energizing currents emanating 20 and controlled from the central station, the telephone sets of any two stations may be brought into connection with one another, intermediate stations may be locked out, or the auxiliary apparatus may be set for purposes of line testing by the central station 25 operator. The auxiliary apparatus also includes main line batteries that are adapted to be brought into operation at times to co-operate with the interchanging apparatus so 30 that when it is desired to cut over stations from one section into another section, the same may be accomplished by the central station operator.

The interchanging station apparatus includes two sets of switch relays and a set of bridging relays, the switch relays being operated one by currents flowing from one side of the station, and the other by currents flowing from the other side of the station, the bridging relays coöperating with the switch relays to effect the necessary bridging over of the line connections of one connection to the connections of an adjacent section, when desired. The interchanging 45 station apparatus also includes two normal line energizing batteries, one of which furnishes the normal energizing current that flows over one section, and the other furnishes the current that flows over another section of the installation. The apparatus at the interchanging station also includes suitable local batteries for taking care of the local circuits. 50

The apparatus of the interchanging station is operated and controlled from the central station by currents emanating over the line wires of either section #1 or section #2, and entering the interchanging station either from one side or the other, as the case may be.

The invention resides in those novel details of construction, combination and arrangement of parts, all of which will be first fully described, and then be specifically pointed out in the appended claims, refer-

ence being had to the accompanying drawings, in which:

Figure 1 is a diagrammatic view illustrating a central station and two sections of installation, with the parts in the normal position. Fig. 2 is an enlarged diagrammatic view of the central station apparatus. Fig. 3 is an enlarged diagrammatic view of the fire and burglar alarm sets of a subscriber's station apparatus, with the parts in the normal position. Fig. 4 is an enlarged diagrammatic view of the auxiliary apparatus at the subscriber's station with the parts in the normal position. Fig. 5 is an enlarged diagrammatic view of the interchanging station with the parts in the normal position. Fig. 6 is a view similar to Fig. 1 showing diagrammatically the relationship between the stations of section #1 and #2 when one of the stations has been cut out on section #1.

In the accompanying drawings, like numerals and letters of reference indicate like or corresponding parts in all of the figures, and Figs. 2 to 5 inclusive, are so arranged that by laying the sheets end to end, the apparatus may be shown in their relative connections.

The apparatus at the central station.—At the central station there is provided a polarized relay, two distinct visual signals and an audible signal, one of the visual signals 457 coöperating with the burglar alarm mechanism at the subscriber's station, while the other 458, coöperates with the fire alarm mechanism, at the subscriber's station. The audible signal 464 is operated when either a fire or burglar alarm is signaled. The polarized relay 450 includes the coils 446 which have two distinct windings and the relay is provided with the usual pole pieces 447 that coöperate with the balanced armature 449.

The armature 449 is provided with lever contacts 453—452 that are in electrical connection with one pole of the local battery 462, the other pole of which is connected by the connection 461 with each of the visual signals 457—458. The signals 457—458 are respectively wired up at 459—460 to fixed contacts 455—456 that coöperate with opposed ones of the levers 453—452 to close the local circuits through the visual signals, as will later more clearly appear. The central station polarized relay is also provided with fixed contacts 454 that are electrically connected by wires 465 with the audible signal 464, such signal also being connected by wires 466—461 with the negative pole of the battery 462. It will be noted that the audible signal is thus adapted to be operated whichever way the armature 449 of the relay 450 is moved over.

Coöperative with the fire and burglar alarm mechanism there is provided in the central station, a hand switch 467 that is

connected in the local circuit of the balancing battery 470. The balancing battery 470 is connected to the local winding of the relay magnets 446 by a wire 471 and is also connected by wire 469 to the contact 468 of switch 467. The switch 467 is also connected by a wire 472 to the local winding of the magnet 446. Thus, there is provided a normally closed balancing circuit through the relay magnets which counter-balances the normal main line current as will be later more clearly understood. One terminal of the main line winding of the coil 446 is connected to the line wire connection 312, while the other terminal is connected to the line wire connection 209 that connects with the contact 544 of another line opening switch 542 which is also connected to the line wire connection 208. 451 is a balancing spring which maintains the balance of the lever 449 when the magnet 446 is deenergized. The central station apparatus is also provided with a telephone set of the usual construction, the hook lever 473 of which normally rests in engagement with contacts 494 and 474 the former contact 494 being grounded through a connection 495 and also connected by a wire 493 to the receiver 491. The receiver is also connected by a connection 492 to the lever 473. The contact 474 connects by a wire 475 with the signal bell 476, that is in turn connected by a wire 477 with the ringer 478. The ringer is connected by a wire 479 to the lever of the line switch 480 and by a branch 485 to a contact 490. The line-opening switch just referred to includes the contact 481 that is connected by a connection 482 to the line wire connection 312 and it also includes a contact 483 that is connected by a wire 484 to the line wire connection 208.

In addition to the foregoing, the central station apparatus, includes two testing signals 503—504, which should preferably be of different types so that the signals may not be confused and for convenience I call one a "buzzer" and the other a "bell" signal. There is also provided a double throw switch 500 which has levers 497—498 and fixed contacts 501—496—499—502 to operate with the respective levers. The contacts 501 and 496 are connected to the buzzer 503 by connections 507—505, respectively, while the contacts 499—502 are electrically connected with the bell 504 by connections 513 and 506 respectively. The lever 497 of the switch 500 is connected by a connection 525 with the line wire connection 312, while the lever 498 is grounded through a connection 541. There are also provided five batteries or sources of energization at the central station. These batteries are numbered respectively 510, 520, 530, 542 and 540 and their circuits are respectively line wire 200 and ground, line wires 200—300,

line wire 300 and ground, ground and line wire 300, and line wires 300 and 200. Battery 510 has its positive pole connected by a connection 512 to the contact 509 of a switch 508 which is in turn connected by a connection 501 with the line wire connection 208. The negative pole of the battery 510 connects to the wire 513. Battery 520 has its negative pole connected by a wire 521 to the wire 507 and its positive pole connected by a connection 519 to the fixed contact 515 of a key 514 which is in turn connected by a wire 522 to the connection 501. The battery 530 has its negative pole connected by wire 528 to the ground connection 541 and its positive pole is connected by a connection 527 to the contact 526 of a key 524 and also by a wire 518 to the lever of a switch 516. The key 524 is connected by a connection 523 with the wire 525 that joins to the line wire connection 312, while the contact 517 of switch 516 is connected to the wire 525. The key 524 is for short circuit closing action, while the switch 516 is adapted to maintain a closed circuit for an indefinite interval of time. The battery 542 has its negative pole connected by a connection 534 with the wire 525 while its positive pole is connected by a connection 532 with the contact 531 of a key 533 that is grounded by the connections 529—528—541. The battery 540 has its negative pole connected by a connection 539 to the line wire connection 208 and its positive pole connected by a connection 538 to the contact 537 of key 535, which is in turn connected at 536 to the wire 525 that runs to line wire connection 312.

The foregoing constitutes a description of one section of the central station apparatus, it being understood that this mechanism is duplicated for each section of installation.

Description of the burglar and fire alarm apparatus at the subscribers' stations.—There is provided at each subscriber's station two sets of apparatus which, for convenience of description, I shall describe as the fire and burglar alarm apparatus and the auxiliary apparatus.

Referring particularly to Fig. 3, it will be noticed that the fire and burglar alarm apparatus includes two circuit controlling switches, —S. A.— and —S. B.— and two main line circuit opening relays M. L. S. C. and M. L. S. D. In addition to the switches and relays there is provided a single telegraph impulsing motor mechanism 209, two distinct sets of circuit closers, one set 32—33 for the fire alarm mechanism, and the other set 34—35 for the burglar alarm mechanism. A main line current impulsing battery 46—47 is provided for each side of the apparatus and there are also provided suitable local signals 50—51 and local batteries 198—199. Each switch —S. A.— and —S. B.—

—S. B.— includes a polarized armature 13 having an arc switching segment provided with alternating contact members 25 and insulating portions 26 to coöperate with the 5 relatively fixed contacts 15—16, 17—18, 19—20, 21—22, 23—24. Each switch is also provided with operating magnets 14 that contain two windings, a local winding and a main line winding. The contact 15 of each 10 switch —S. A.— and —S. B.— is connected to one terminal of the local winding of the operating magnets 14. Each of the contacts 17 of the switches is connected by a wire 186 to a wire 197 that leads to the motor 209. 15 The contacts 23 of the respective switches are connected by wires 178 and 181 respectively with the local signals 61 and 50. The contacts 16 and 18 of switch —S. A.— are connected together to a wire 189 which leads 20 to the battery 198. The contact 24 of switch —S. A.— connects by a wire 177 with the wire 189 and with the wire 173, the wire 173 connecting the negative pole of the battery 46 with the contact 39 of main line switch C. 25 The contact 21 of switch A connects by a wire 215 with the contact members 214, on the signaling disk 212, the main line opening relay 28 having its coil connected in the circuit of the wire 215. The contact 22 of 30 switch A is connected by a wire 192 with the main line wire connection 307, and also by a connection 95 to one terminal of the main line winding of the operating magnets 14, the other terminal of which connects by a 35 connection 112 with the armature 138 of the quick-acting relay 28. The contact 143 of this relay connects by a wire 113 to contact 19 of switch —S. A.— The contacts 20 of the switches A and B connect by a connection 40 165 with the contact 38 of the respective main line switches C and D.

Each of the switches A and B is provided with a contact 27, the contact 27 being connected by a connection 183 with 45 the coil 36 of the respective main line switches C and D, the other terminal of its coils being connected together by a wire 184 which is also electrically connected with the local battery 199. The positive pole of 50 the battery 199 is connected by wires 79 with the respective armatures 13 of the switches A and B.

The burglar alarm contact members 35 are connected together by a connection 169 55 which connects with the wire 172 that joins the positive pole of the battery 46 with the fixed contact brush 218 that coöperates with the signaling disk 212. The contacts 34 of the burglar alarm circuit closers are joined 60 together and connected by a wire 175 with one terminal of the local winding of the coils 14 of switch A. One set 33 of the fire alarm circuit closer contacts is connected together by a wire 171 which joins 65 to one terminal of the local winding of the

magnets 14 of switch B, while the other contacts 32 connect by a wire 170 with the wire 187 that joins the positive pole of the battery 47 to the brush 220 that coöperates with the signaling disk 211. 70

If desired, a polarized magnet 29 may be provided to coöperate with one of the magnets 14 of switch A and in that event the armature 29 is connected by a wire 227 to the positive pole of battery 198 and by a 75 connection 228 to the wire 169. A fixed contact 30 may coöperate with the armature 29 and connect by a wire 180 to the wire 175 for a purpose later understood. The contacts 213 of the signaling disk 211 are connected by a connection 219 (through the coil of the quick-acting relay 31) to contact 21 of switch B, the contact 22 of which is joined by a wire 193 to the main line wire connection 204 and by a wire 194 to the contact 132 of the quick-acting relay 31, the armature 231 of which is connected by a wire 195 with one terminal of the main line winding of the magnets 14 of switch B, the other terminal of which is connected by a 80 wire 232 to the contact 19 of that switch. The contact 24 of switch B is connected by a wire 182 to the wire 188 that connects the contact 39 of main line switch D with the negative pole of the battery 47. The contact 16 of switch B is connected by a wire 191 to the wire 182 and the contact 18 of that switch is connected by a wire 190 to the wire 189 that joins with the negative pole of the battery 198. 85

Each main line switch C includes the operating magnet 36 and the armature 37, and the three active contacts 38, 39 and 40. The contact 40 of the main line switch C is connected to the main line wire connection 205, while the contact 40 of switch D is connected to the main line connection 308. The armature 37 of main line switch C connects to the line wire connection 204, while the armature 37 of main line switch 110 D connects to main line wire connection 307. The main line wire connection 204 connects with the terminal changing switch of the auxiliary apparatus (hereinafter referred to), by the wire 42, the connection 115 being made via post 5, while the wire 41 from that terminal changing switch connects to the post 6 to which the line wire 200 joins. The line wire connection 307 joins with, the said terminal connection changing switch by a wire 83 via post 11, while the wire 84 from that switch connects to post 12 to which the main line wire 300 is joined. 120

While I have described the provision of 125 quick-acting relays 28—31, I desire it understood that they may be omitted if desired. The function of these relays, however, is to insure the full force and effect of the main line current signaling impulses being sent 130

out into the main line by the batteries 46—47, as the case may be. The signal 51 is connected by a connection 179 of the contact 216 of the disk 212, while the corresponding contact 217 on the disk 211 connects by a wire 185 with the signal 50, it being understood that the signals 50—51 are of different types so as to signalize the burglar and fire alarms distinctly. The armature 13 of the switches A and B is polarized so as to be thrown in either direction, depending upon the direction of current through the magnets 14.

The auxiliary apparatus.—Each station is provided with an auxiliary apparatus for line testing and telephonic purposes, which apparatus also is provided with means for coöperation with the controlling instrumentalities at the central station for changing over the main line connections of the subscriber's station when it is necessary to cut a station from one section of installation into another section of installation. The auxiliary apparatus of each subscriber's station includes a set of bridging relays B. R. E., two sets of switch relays, one, S. R. H., controlled from the central station by currents passing into the auxiliary apparatus from the right of Fig. 4 and the other, S. R. I., being controlled by currents passing into the auxiliary apparatus from the left in Fig. 4. In addition to the switch relays and the bridging relays, there is provided a main line terminal switch F, and a second switch G which is provided for the purpose of cutting in the auxiliary normal main line batteries 95—96, under certain conditions, as will later more clearly be explained. The auxiliary apparatus also includes two local circuit batteries 97—98 and a telephone set T.

By reference to Fig. 4, the wiring of the auxiliary apparatus will be understood. 1—2—3—7—8 and 9 designate terminal posts, which have been indicated for convenience. The main line wires 200—300 from the left of Fig. 4 connect to the posts 1 and 7 respectively. The post #1 is connected by a wire 48 to two contacts 1 on the switch F (the reference characters 1 to 12 inclusive on the switch F are the same as the numbering of the respective terminal posts, for convenience in following the connections between the same). Obviously, the terminal posts may be omitted and the wiring run direct to the switch but they are indicated simply for convenience of illustration. The post 2 connects by wire 49 with a set of contacts 2 of the switch F; post 3 connects by wire 44 to contacts 3 of the switch F; post 4 connects by wire 43 to contacts 4 of switch F; post 5 connects by wire 42 to contacts 5 of switch F; post 6 connects by wire 41 with contacts 6 of switch F; post 7 connects by wire 52 with contacts

7 of switch F; post 8 connects by wire 53 with contacts 8 of switch F; post 9 connects by wire 45 with contacts 9 of switch F; post 10 connects by wire 55 with contacts 10 of switch F; post 11 connects by wire 83 with contacts 11 of switch F and post 12 connects by wire 84 with contacts 12 of switch F. It is understood that posts 4—5—6 and 10—11—12 are the posts of the burglar and fire alarm sections and are indicated in Fig. 3. The switch F has a polarized armature 70 which is fulcrumed at 71 and is provided with operating magnets 88—89, each of which serves as a relay to coöperate with the respective armatures 90—92 that control the circuit connections between the contacts 91—93 and 94 respectively. The armature 70 of the switch F is provided with an arc segment having alternately disposed contacting and insulating segments, as clearly shown in Fig. 4 of the drawings. The switch G is similar in construction to the switch F. It also has a polarized armature 54 and an arc member which is provided with alternately disposed insulated sections 56 and contacting sections 57 to coöperate with the several sets of fixed contacts 58—59, 60—61, etc. The magnets 66—67 of the switch G are double wound-magnets and one of them, 66, acts also as a relay magnet to coöperate with the polarized armature 80 that normally rests on the fixed contact 81. The contact 59 of switch G is connected by wire 280 with the auxiliary main line battery 95, such battery being also connected by wire 281 to the contact 63. The contact 59 is also electrically connected to the wire 202 which runs to the contact 115 of the bridging group (B. R. E.). The contact 58 which opposes the contact 59 is electrically connected to the contact 60, and by a wire 203 the contacts 58—60 are connected to the terminal post 2. The contact 61 is connected by a wire 283 to the battery 96, which also is connected by a wire 282 to the line wire connection 304. The contacts 77 and 76 are electrically connected together and by a wire 278 that connects with the wire 255. The contact 68 which opposes the contact 77 is connected by a wire 287 to the second or lower winding of the coils 67—66, such winding being also connected by the wire 82 to the polarized armature 80. The contact 69 which opposes the contact 76 is connected by a wire 285 with the upper or first winding of the magnets 66—67, such winding being also connected by the wire 230 to the contact 72. The contacts 73—75 are connected together and by a wire 277 they are electrically connected with the contact 94 of the switch F. The contact 74 which opposes the contact 75 is connected by a wire 78 to the contact 81 of the switch G. The contacts 62—64 are connected together to the line wire connection 303. The contact 65 is

connected to the line wire connection 304. The bridging relays include the main local holding magnets 101—102, the windings of which are connected together by a connection 293. The coil of relay 101 is connected by a wire 291 with the negative pole of the local battery 97, while the coil of relay 102 is connected by a wire 294 with the coil of relay 130 of switch relay S. R. H. The bridging relay group also includes the three armatures 103—104—105 and the local holding relays 99—100 that coöperate with the armatures 105—103 respectively. The magnets of the relays 99—100 serve as holding magnets to coöperate with the armatures 108—106 respectively to break the circuits through the same at the contacts 109—107, as will later be more clearly understood.

111—118 are holding magnets for the armatures 105—103 respectively. These magnets operate by main line and ground return currents and do not operate by local circuits, and the bridging relay group B. R. E. also includes a double wound 25 setting magnet 110 which is operated by main line currents as will later be explained. The main line wire connection 202 runs to the contact 115 of armature 105 while the contact 114 of that coöperates with that armature is connected to the winding of magnet 111 and also to the main line connection 245 which runs to the armature 138 of switch relay group S. R. H. The winding of magnet 111 is also connected by a wire 246 with armature 92 of switch F, while the contact 93 of switch F is connected by the wire 247 with the armature 108 of the bridging relay group. Contact 109 is connected by a wire 248 with the main line circuit opening magnet 144 of the switch relay S. R. H. The coil of relay 118 and the contact 117 are connected by wire 260 with the armature 141 of switch relay group S. R. I. The winding of magnet 118 is also connected by wire 259 with the armature 90 of switch F, the contact 91 of which switch being connected by wire 258 with an armature 106 of the bridging relay group. The contact 107 that coöperates with armature 106 is connected by wire 254 with the coil 144 of the relay of group S. R. I.

One winding of the relay 110 is connected by wire 274 with the core of holding relay 128 (group S. R. I.) and it is also connected by wire 273 with the main line wire connection 203. The other winding of the relay 110 is connected by wire 275 with the armature 105 and by wire 276 it is connected to the core of holding relay 128, group S. R. H. The armature 103 is connected by wire 279 to the wire 273. The armature 225 is connected by a wire 87 to the contact 86 and by a connection 243 to the line wire connection 202, while the contact 226 is connected by a wire 244 to the contact 139, group

S. R. H. Each switch relay S. R. H. and S. R. I. includes a main operating magnet 119 and two polarized armatures 120 and 121 respectively, these armatures coöperating with the pole pieces 118—119 and with holding relays 127—128 and resting relays 129. The group S. R. H. differs from the group S. R. I. in that the former is provided with a resting relay 130 while the latter is provided simply with a stop 334 in lieu of the resting relay. The coils 119 of each switch relay group S. R. I. S. R. H. are connected to the respective contacts 132 and 142, and the contacts 126 of each group are connected by wires 268 to the main line 80 wire connections 203—202 respectively. Each contact 125 is connected by a wire 262 with the contact 150.

Referring particularly to switch relay group S. R. H. it will be noticed that the contact 133 is connected by a wire 256 with the winding of the magnets 88—89 which winding is also connected by a wire 255 to the wire 253. The contact 134 connects by a wire 263 to the contact 149. The contact 135 of group S. R. H. connects by a wire 266 to the contact 148 which is in turn connected by a wire 264 to the line wire connection 301. (The contact 135 of switch relay group S. R. I. connects by a wire 257 to the wire 256). The armatures 121 are each provided with insulated contacts 123 that are connected together by wires 269, such wires 269 being electrically connected by a wire 270 to the telephone contact 166. Each armature 121 is also provided with an insulated section 122, the insulated sections of the two armatures 121 being connected together by a wire 297 that is in turn connected by a wire 296 to the positive pole of the local battery 98, the negative pole of which is connected by a connection 320 with the coil 99 of the bridging relay group B. R. E., such coil 99 being also connected by a connection 319 with the contact 137 of group S. R. H. The armature 136 of group S. R. H. is electrically connected to the wire 296, while the armature 136 of group S. R. I. is electrically connected by a connection 318 with the coil of bridging relay magnet 100, such magnet being in turn connected by a wire 317 to the positive pole of the local battery 98. The armature 131 controls connection between contacts 132—134 and 133—135 respectively, while the armature 136 controls connection with the contact 137.

The line wire connection 244 between the contact 226 of the bridging relay group B. R. E. and the contact 139 of the switch relay group S. R. H. coöperates with the armature 138 of the local resting relay 130 one terminal of the winding of which is connected to the coil 102, by connection 294 as before described, while the other terminal is connected by a connection 295 to the core 125 120 123 125 126 127 128 129 130 131 132 133 134 135 136 137 138 139 140 141 142 143 144 145 146 147 148 149 150 151 152 153 154 155 156 157 158 159 160 - of the relay so as to effect the electrical contact with the armature 120 under normal conditions. The armature 120 of group S. R. H. is electrically connected by a wire 5 333 to the contact 334 of group S. R. I. by a local circuit connection, the armature 120 of group S. R. I. being connected by a local circuit wire 289 to the wire 288 which runs to the positive pole of the local battery 97.
- 10 The armature 121 of the switch relay groups are electrically connected by connections 288—290 to the positive pole of the battery 97. The armature 120 of the switch relays S. R. H. and S. R. I. is provided with a 15 contact 124 that is adapted, at times, to engage the fixed contact 125, such contact 125 being electrically connected by a connection 262 to the contact 150 in the main line circuit. Each contact 221 of the switch 20 relay groups S. R. H. and S. R. I. is connected by a connection 222 to the contact 223. The connection between the contacts 223 and 148 is adapted to be made by the insulated portions 224 of the armatures 145 25 when such armatures are drawn over into contact with the contact 147. The resting relay 129 of group S. R. I. has one terminal 298 connected to the core, and the other terminal 314 connected to the contact 137 which 30 is in turn connected by a wire 316 to the negative pole of the local battery 98. The corresponding terminal of the coil 129, group S. R. H. is also connected to the wire 316 by a connection 299. The coil 128 group 35 S. R. I. has one terminal connected to the core, as at 323 and the other terminal connected by a connection 324 to the wire 321 which runs from the coil of relay 127, group S. R. I. to the armature 104 of the bridging 40 relay B. R. E. The coil of relay—127, group S. R. H. also connects to the armature 104 by virtue of the connection 325, with the wire 324. The coil of each of the respective relays 127—129—130—128 is connected 45 electrically with the respective cores of such relays to coöperate electrically with the armatures 121 and 120.
- The normal main line circuit which passes 50 from the interchanging station's battery enters the auxiliary apparatus and at post #1, flows via connections 48—49 to post #2 and from thence through connections 203—202, 243 to armature 225 and from thence to contact 226 and thence over wire 244 to contact 55 139. From contact 139 the current flows to armature 138 and from thence via wire 245 to contact 114, across armature 105 via main line connection 201 post #3 wires 44—43 to post #4 and from thence through the 60 burglar and fire alarm section of the apparatus as before described. Returning, the current enters the auxiliary apparatus from post #10 over wires 55—45, to post #9, and from wire 301 to armature 146 (group 65 S. R. H.) across to contact 150, over wire 302 to key 152 and across to contact 156. From contact 156 the current flows over wire connections 303—304 to contact 155 of key 151, across key 151 to connection 305 and from thence to contact 150 (group 70 S. R. I.), across armature 146 and line wire connection 306 to post #8 and from thence over wires 53—52 to post #7 and out into the main line 300. The keys 151—152 have contacts 153—154 respectively which are 75 connected by a connection 329 and also have contacts 157—158 respectively which are connected by a connection 271, this connection being also connected by a wire 272 to the telephone contact 166. The contact 155 80 of key 151 is connected to the contact 148 (group S. R. I.).
- The telephone set is of the usual type and includes the lever 159, the receiver 160, the magneto 167 and the ringer 168. The 85 lever 159 normally engages a grounded contact 161 which is grounded through a connection 252 to which the telegraph instrument is electrically connected and to which the contact stud 164 is connected by a connection 251. The contact 162 connects by a connection 251. The contact 162 connects by a connection 330 with the ringer 168 and magneto 167, the latter being connected to the wire 270. The wires 253—249 connect 90 through 250, the circuit between the studs 164—165 being held closed by contact 163 pressed up by the telephone lever. It should be understood that the contacts 224 of armature 145 are insulated from the rest of the 100 armature so as not to be in electrical connection with the same, as such contacts are simply bridging contacts, as it were, for the fixed contacts 148 and 223 respectively.
- The apparatus at the interchanging station.*—The interchanging station contains an apparatus which has two substantially distinct groups of mechanism, one being operated by current impulses entering the station from one side, while the other is operated by current impulses entering the station from the other side. The interchanging station apparatus includes two switch relays S. R. K. and S. R. L. and a group of bridging relays B. R. J. that coöperate with the 110 respective switch relays. In addition to these there is provided two main line normal current producing batteries that serve as line terminal sources of energy for the main line circuits that enter the station from each side under normal conditions. There is also provided local circuits coöperating with the switches and bridging relays for assisting in the operation of the same. The group of bridging relays B. R. J. includes a double wound resetting relay 358 operated by main line circuit currents, two other relays 336—337 also operated by main line currents 115 two local operating relays 338—339 and two local holding relays 340—341. Coöperating 120

- 130

with relays 340—338—336 is an armature 342. A second armature 344 coöperates with the corresponding relays 337—339—341, the armature 344 and the relays 337—339—341 5 coöperating directly with the switch relay K, while the armature 342 and the relays 336—338—340 coöperate directly with the other switch relay L, the relay 358 coöperating with both switch relays K and L, as 10 does also the armature 343, the armature 343 also coöperating with the relays 358—338. The relay 336 is provided with a second armature 347 that is connected by a connection 424 with the main line connection 207 that also connects to the armature 342. The contact 351 of relay 336 is joined by a connection 421 to a wire 422 that connects the contact 354 of relay 340 to the contact 357 of relay 341. The relay 337 is also provided with a second armature 348 that connects by a connection 419 to the wire 420 which joins the contact 356 of relay 341 with the contact 355 of relay 340, the relays 340—341 having two "dead" stops and two 25 live contacts, as indicated, and each relay 340—341 is provided with an armature 345—346, respectively, and the contact 353 of relay 337 is joined by a wire 423 to the armature 344 to which armature the main line wire connection 206 is joined. The armature 343 is coöperative with a local circuit contact 352 that joins by a wire 435 to the wire 434 which connects the negative pole of the local battery 425 with the coil 338, the coils 338—339 being connected together by a connection 433 while the coil 339 is connected by a connection 432 to the coil of local relay 365 of switch S. R. K. 30 One terminal of the winding of relay 336 is connected by a wire 416 with one winding of the coil or relay 367 of switch S. R. L., while the other terminal of the winding of the coil of relay 336 is joined to a contact 349 that coöperates with the armature 342 and is electrically connected at 415 with the contact 381 of switch S. R. L. The coil of relay 337 has one end connected by a connection 413 to one coil of the relay 367 of switch S. R. K., while the other terminal of the coil or relay 337 is joined to the contact 350 that coöperates with the armature 344 and is also connected by a connection 414 to the contact 381 of switch S. R. K. 35 Armature 343 is electrically connected to a wire 442 of the local circuit, while the contact 352 that coöperates with the armature 343 is connected to the wire 435, as before stated. Each switch relay K and L includes a main operating relay magnet 359 having poles 362—363 and provided with polarized armatures 360—361. Each switch group also includes a holding relay 364 for the armature 360, a holding relay 366 for the armature 361 and resting relays 365. The switch relay K is also provided with a resting relay 368, while the switch relay L has a contact 386 in place of the resting relay. Each switch relay group also includes the double wound main line relays 367 and the resetting relays 242. The relay 368 has an armature 387 and contacts 388—389 while the holding relay 364 of each relay K and L has an armature 369 and four contacts 370—371—372 and 373. Each resting relay 365 has an armature 375 and a contact 376, while each holding relay 366 is provided with an armature 377 and four contacts 378, 380, 379, 381. The holding relays 366 are double wound, they each having a local circuit winding and a main line circuit winding. Relays 368—364—365 are purely local circuit relays. The one terminal of the coil 359 of each switch relay K and L is connected by a wire 401 to the contact 379, the other terminal of the coil 359 being connected by the wire 394 to the contact 371. Contacts 374 are provided to coöperate with the armature 361 and they are connected by wires 393 to the contacts 373. The core of relay 366 of S. R. K. is joined by a wire 402 to one winding of the relay 358 of the bridge relay group J, the other terminal of this winding being connected by a wire 404 to the main line wire connection 309. The core of relay 366 (bridge relay group L) is 40 connected by a wire 403 to the other coil of the magnet 358 which other coil is also connected by a wire 405 to the main line wire connection 311. The contacts 372 are connected by wires 395 to the contacts 384 and the contact 370 of S. R. K. is connected by a connection 417 to the armature 387, which is in turn connected by a connection 412 to the main line wire connection 309. The contact 378 of each switch relay K and L is connected by a connection 400 to the contact 385 while the contact 380 is connected by a connection 397 to one winding of the coil of relay 367, the connection 397 also connecting with the wire 410 that leads to the contact 240 of the relay 242. One terminal of the main line coil of holding relay 366 is connected by a connection 399 to the ground, while the other terminal of this coil is connected to one of the windings of coil 367. This winding of the coil 367 in S. R. K. is connected by a wire 413 with the coil of the relay 337, while the corresponding coil of S. R. L. is connected by a wire 416 to the coil of relay 336. 50 55 60 65 70 75 80 85 90 95 100 105 110 115 120 125 130

391 is the main line normal energizing battery for the circuit whose line terminal enters the interchanging station from the right in Fig. 5, and this battery has its negative pole connected by a connection 407 to the main line connection 309 and its positive pole connected by a connection 406 to the second winding of the relay 367, that winding being the one that connects by the connection 397 to the contact 380. 392 is 130

the corresponding main line battery for sending out the normal main line current to the line circuit whose terminals enter the interchanging station from the left in Fig. 5. 5 This battery, like the battery 391, has its negative pole connected to a main line connection (310) and its positive pole connected by the wire 406 with one of the coils of the relays 367 being the coil that connects 10 by the wire 397 to the contact 380 of that switch. Each of the armatures 382-383 of the respective switches 367 are connected together, by a connection 396, to the respective contacts 381 and the contacts are connected by wires 414-415 respectively to the contact 350-349 respectively of the bridge relay group J. The contacts 372 of the switch relay 364 connect to the respective contacts 384 by connections 395, while the 20 contacts 385 connect by the connections 400 to the contacts 378, as before stated.

The armature 387 co-operates with two contacts 388-389, the former connecting with a wire 411 to a coil 242, the said coil 25 being grounded by a connection 409, as before stated, while the contact 389 connects to the main line wire connection 310. The armature 239 of switch S. R. K. connects by a connection 241 to the wire 412, while the armature 239 of S. R. L. connects by a connection 241 to the line wire connection 310. The coil of relay 242 of S. R. L. connects with a wire 237 to the wire 236 that joins the two contacts 234-238 that co-operate 35 with the armature 360 of (S. R. L.). The other terminal of the coil 242 is grounded through a connection 409.

425 is the local circuit battery, the positive pole of which is connected by a connection 428 with the armature 360 (S. R. K.) by a connection 426-427 to the armature 361 (S. R. L.), and by a connection 426 with the contact 390 (S. R. L.). The batteries 391-392 also function at times as 45 local batteries. The main line battery 392 is electrically connected, locally, by a wire 441 with the coil of relay 340, the said coil being also connected by a wire 439 with the armature 375 (S. R. L.), the contact 376 50 that co-operates with such armature being connected by a wire 437 to the positive pole of the battery 392. The battery 391 has its negative pole connected, locally, by wire 440 with the coil of relay 341, such coil being 55 also connected by a wire 438 with the armature 375 (S. R. K.) the contact 376 that co-operates with such armature being connected by a connection 436 with the positive pole of battery 391. The coil of each of the 60 relays 364 is connected to its core, as is also the winding of relay 368, such winding of relay 368 being connected by a connection 429 to the negative pole of battery 425. The coil of relay 364 (S. R. K.) is connected by 65 a connection 443 to the wire 442 that con-

ncts to the armature 343. The coil of relay 365 of each switch is connected to its core and the coil of relay 365 (S. R. K.) is connected by a wire 432 to the coil 339, such coil 339 being in turn connected by a connection 433 with coil 338 which connects, by a connection 434, with the battery 425. The local winding of each relay 366 has one terminal connected with the core of the relay and the other terminal connected by a connection 445 and 443 respectively to the connection 442 with the armature 343. The main line wire connection 311 joins with the terminal post 170 at the left of Fig. 5, while the connection 309 joins with the terminal post 170 at the right of Fig. 5. Similarly the line wire connections 206-207 connect to the terminal posts 169.

On operation of the burglar alarm mechanism.—Assume now that one of the burglar alarm contacts 34 is moved to close the circuit with contact 35 of a particular station. The instant this occurs, the local battery, 198, will send out a current over wires 227 and 228 to circuit closer contact 35. 90 From contact 35 the current flows across contact 34 and travels over wire 175 through the local winding of coils 14 (S. A.), to contact 15, over armature contact 25 to contact 16, and return to battery over wire 189. 95 This establishes a circuit which will energize the coils 14 and rock over the armature 13 of switch S. A. to rest on stop contact 27. At the instant the circuit is closed through the contacts 34 and 35, and the magnet coils 14 energized, the lever 29 is attracted to engage the contact 30 and shunt a portion of the local current over wire 227, through wire 180 to wire 175 and thereby maintain the local circuit current through the magnet coils 14 until the circuit is broken by the armature 13 rocking over into engagement with the stop 27 to bring an insulated portion between the contacts 15 and 16. This takes care of the condition 110 which would exist were the circuit immediately broken at the contacts 34 and 35, so as to insure a sufficient energizing of the magnet coils 14 to throw the armature over, even though the circuit be but momentarily 115 closed at the contacts 34 and 35. If the local circuit from the battery 198 via contacts 34-35, or via relay contacts 29-30, is not sufficient to throw over the armature 13 to its working place, the main line battery 46 is brought into operation to make a short local circuit before being used for signaling purposes *i. e.* before the path from the battery 46 is opened up to the central station. 120

The momentary circuit afforded by the main line battery, only comes into action in the event that the local circuit has not completed the throwing over or rocking over of the armature 13 to its working position. If 130 the armature remains in its normal position,

a circuit will be established from the main line battery 46 via wires 172-169, across contacts 34-35 (which are still closed and across contacts 29 and 30 via wire 228, if the previous currents have been sufficient to draw up said armature) through the local winding of coils 14, via contacts 15 and 16 and wire 189 to wire 177 and from thence over wire 173 back to battery 46. This last current will be sufficient to throw the armature 13 over (and draw up the armature 29 if it has not risen), and the use of the main line battery 46 for establishing this local circuit may or may not be taken advantage of. It is illustrated to show that the main line battery may, while otherwise idle, be employed for this purpose. Now assume that the armature 13 of switch (S. A.) has been thrown over on to contact 27. This opens a new path for the local circuit from battery 198 at the same time the first local circuit, above described, is broken by an insulated portion 26 of the arch member coming in between the contacts 15 and 16. The new circuit now opened up has for its object to start the motor 209 into action. This circuit emanates from the local battery 198 and passes via wire 196 to motor 209 and from thence over wires 197-186, contacts 17 and 18 (which are now in circuit), wire 189 back to battery 198. This current starts the motor into operation to turn the signaling disks 211 and 212 and remains in operation as long as the circuit is closed between contacts 17 and 18.

When the armature 13 of switch (S. A.) was rocked over to rest on contact 27, a circuit was closed between it and the stop contact 27, thereby permitting a current to flow from the battery 199 via wire 79, armature 13, stop 27, wire 183, to magnet 36 of the main line switch C, and from thence back to battery via wire 184. This circuit is kept closed until the apparatus is reset. The coil 36 of the relay (M. L. S. C.) having become thus energized, draws over the armature 37 to engage the contacts 38-39. The local circuit through the motor 209 starts it into operation, as before described, thereby turning the signaling disks or wheels 211 and 212 to successively bring the various contacts 217-216 and 213 and 214, into engagement with the fixed contacts 220 and 218, respectively. Every time one of the moving contacts comes into engagement with the fixed contact, a circuit is closed at those contacts. When the contacts 214 engage the contact 218, the circuit of the battery 46 is closed and current flows from battery 46 via wire 172, contact 218, contact 214, wire 215, through coil 28 of the quick-acting circuit opening relay, via wire 215, contacts 21-25-22, wire 192 to line wire 307 and from thence through the line wire connections 83-84 to line wire 300, over line wire 300

to the central station, the current returning over wire 200, enters the station over line wire connections 41-42, 204 and flows to armature 37 from thence across to contact 39 and return to battery 46 over wire 173.

When the quick-acting relay 28 is provided, no current will flow from wire 192 through coils 14 during the signaling impulse of the signaling wheel. The relay may or may not be used, as desired. It is understood that the current flows from the signaling station through any intermediate stations that are set in normal position, to the central station. The current passes through the central station apparatus 80 through wire 312, to wire 208 via the main line winding of relay coils 446, wire 209 and switch 543. The instant the line wire connection was broken at the signaling station between the armature 37 and the contact 40, the normal energizing current in the main line circuit was broken, with the result that armature 449 at the central station was drawn over to one side to close the circuit to the bell 464, by reason of the energization of the coils 446 by the current from battery 470. As soon as the central station operator has been thus warned, he opens the switch 467 so that the influence of the battery 470 at the central station, may be nullified. The impelled current from the signaling station telegraphs the burglar telegraphic signal of that station by current impelled through the main line winding of magnets 446, thus accordingly closing the 100 circuit to battery 462 to ring the bell 464 and light up the lamp 457. It will be observed that the action of the signaling wheels 211-212 is alternately to signal the central station and to ring the audible signals 50 or 105 51, at the subscriber's station. The latter act for signal 51 is accomplished when the contact 216 engages the contact 218 to close the circuit from battery 46 through wires 172, 179, 178, 177, 173. Were the quick-acting relay 28 not employed, the main line signaling current would divide where the wire 95 joins the wire 192 and a portion of it would flow through the coils 14. While this current would not effect the position of 110 the switch A after it has once been thrown, because it is in the same direction as the throwing current, nevertheless by using the quick-acting relay 28 the flow of this current will be suspended so as to permit the 115 full potential of the battery 46 to act on the main line impulses.

Operation of central station apparatus on burglar alarm signal.—The burglar alarm contacts 34-35 of some protected premises, 125 (say station #2) having been closed and a current sent out via main line wire 300 and return via wire 200, from main line battery 46 of that station, as before described, a circuit has been closed at the central station. 130

It should be understood right here that the contact wheels 211—212 of each station have their contacts 213—214 differently arranged at each station, so as to have each station give a different telegraphic signal in any desired code. The current entering the central station, as before described, passes over the line wire connection 312 and through the operating or main line winding of the polarized relay 450, passing through coils 446, as before described. The lever 449 of the polarized relay is normally balanced by the springs 451 and the balancing battery 470. When the burglar alarm signal of telegraphic impulses comes in and the main line current passes through the coils 446, the lever is attracted at, say the right hand coil. This causes the lever 453 to close against the circuit contacts 454—455 thereby permitting the local battery 462 to send out a current via wire 463, lever 453, contact 454, wire 465 to audible signal 464 and return via wires 466 and 461. The local battery 462 also sends out a current via contact 455 and wire 459 to the visual signal 457 and return via wire 461. Thus each impulse that is received in the central station causes a corresponding operation of the audible and visual signals at that station. This operation continues to occur, indefinitely, until the watchman at the central station has noticed the signal and reset the instruments, as will be hereinafter described.

I desire it understood that while I have indicated the visual signals as incandescent bulbs, and the audible signals as bells and buzzers, nevertheless any standard type of signal that may be desired can be employed in lieu thereof.

40 *Resetting of the burglar alarm signaling apparatus at the subscribers' stations.*—In order to reset the apparatus which has been sending in the burglar alarm signal, I have provided, at the central station, a battery 520 and key 514. Upon depressing the key 514, a circuit is closed from the battery 520, which causes current to flow via wire 519, contact 515, key 514, wires 522 and 501 to line wire connection 208 (switch 543 is now 45 opened) out over line wire connection 208 into line wire 200 and return via line wire 300 into the central station, over wire 525 to lever 497 of switch 500, contact 501, wire 507 and return to battery over wire 521. 50 This current will flow whenever an insulated portion of the disk 212 is in engagement with the contact 218. When this occurs, the current enters the subscriber's station over line wire connections 41, 42, 204 55 and flows to lever 37 of the relay switch C. From the lever 37 the resetting current flows to contact 38 over wire 165, across contacts 20—25—19, through wire 113 to contact 143, across lever 138 (magnet 28 being deenergized when the insulated portion of the disk 60

212 is in engagement with the contact 218), over wire 112, through the second winding of coil 14, over wire 95 to wire 192 and from thence to line wire connection 307 and over wires 83—84 to line wire 300 and return to 70 central station. The resetting current flowing through magnet 14 of switch A is in a direction opposite to the setting current and therefore reverses the polarity to restore the armature 13 to its normal position and thereby break the various circuit connections at such switch. The breaking of these circuit connections cuts out the motor battery 198 from action and allows the signaling motor 209 to come to rest. This having been accomplished and no other currents coming into the central station, the central station operator now resets the normal line battery 391 at the interchanging station, as will be hereinafter understood (after closing switch 85 543) and then again closes switch 467 to re-establish the balancing current in the signaling relay 450 at the central station.

75 *Operation of the fire alarm mechanism.*—The operation of the fire alarm mechanism 90 is essentially the same as that of the burglar alarm mechanism save only that the fire alarm side of the apparatus comes into action instead of the burglar alarm side, and in view of the foregoing description of the burglar alarm mechanism, it is thought that the operation of the fire alarm mechanism will be clearly understood by reference to the drawings, and a detailed description thereof is thought to be unnecessary. Supposing station #1 is sending in over a burglar or fire alarm signal to the central station, and station #10 should begin to send fire or burglar alarm telegraphic impulses, the impulses of station #10 would 100 not be received at the central station, owing to the opening of the main line circuit at station 1, contact 40, switch C and the signal of station #10 would not be received until the central station operator has reset 105 station #1 and as soon as station #1 has been reset to close the main line circuit at contact 40, switch C, the current from station #10 will immediately come into the central station.

110 *Operation of the central station apparatus on fire alarm signal.*—Since the operation of the central station apparatus is substantially the same on fire alarm signals as on burglar alarm signals, save only that the visual signal 458 is operated in lieu of the signal 457 and the contacts 454—456 are engaged in lieu of the contacts 454—455, a detailed description of the operation of the central station apparatus on fire alarm signal is 115 120 thought to be unnecessary.

125 *Resetting of the fire alarm apparatus.*—In order to reset either the fire or burglar alarm apparatus it will be noticed that the current sent out from the central station 130

must flow in the same direction in the line wires as the signaling current. Therefore, in order to reset the fire alarm apparatus the signaling current flows from the central station over wire 300 and return, over wire 200 (the reverse of the burglar alarm current). It is necessary to close the circuit at the central station from battery 540. This is done by depressing the key 535, (after 5 opening switch 543) which causes current to flow from the battery 540 via wire 538, contact 537, key 535, wire 536, wire 525, line wire 300 and return to central station over wire 200, line wire connection 208 and 10 wire 539 to battery 540. The current enters the subscribers' station over line wire connections 84, 83, 307 and flows to armature 37 (switch D) and flows to contact 38 from thence it passes via wire 165, contacts 20, 20 25, 19, wire 232, resetting winding of coils 14 switch B, wire 195, armature 231, contact 132, wire 194, through wire 193 to line wire connection 204, over line wire connections 42—41 to line wire 200 and return to central 25 station. This current, being in a direction reverse to the current that threw over armature 13 of switch B, will reverse the polarity and restore the armature 13 to its normal position and consequently reset the apparatus. 30 It will be observed that when either the burglar or fire alarm mechanisms are operated, the main line circuit to all stations beyond the particular station operating is broken at the switches C or D, as the case 35 may be, and thus when that station signaling, which is nearest the central station, has its signal impelled to the signal station; the remaining stations' signal being received at the central station successively as the preceding station's signal has been noted and such preceding station has been reset. 40

Operation of the auxiliary apparatus for the purpose of line testing.—Should a break in the lines occur or any interruption of the 45 normal constant current that flows through the lines, the balancing battery 470 will function to throw over the armature of the relay to close the circuit to the signal 450, thus indicating to the central station opera- 50 tor that there is trouble on the line. The indication of trouble having come in (or regard- 55 less of a previous trouble indication, if the central operator desires to test the lines at any time) the operator at the central station closes the circuit at switch 508 and leaves it there until the end of the testing 60 operation for each station and also opens switch 543. The closing of this switch 508 results in the setting up of a current from battery 510 which flows over wire 512, switch 508, wire 501, into main line connection 208 of the central station into line wire 200 and over that line wire into the first station apparatus (station A). For convenience, we 65 will first follow the current as it flows

through the auxiliary apparatus of station A. It enters the station over line wire connection 42, 41, 204, 205, 43, 44, 201 and passes via lever 105 to contact 114 and from thence it flows through sustaining or holding relay 111 and along wire 246 to armature 92, and contacts 93 and from thence over wire 247, armature 108 of relay 99 across same to contact 109 and via wire 248 through the winding of relay 144 (S. R.—H.) 70 flowing from thence over wires 249 and 250 to telephone stud 165, across the spring contact plate 163 to stud 164 and from thence via wires 251 and 252 to ground, returning via the ground connection 541—513 to the 80 negative pole of battery 510 at the central station. At the instant that the lever 146 of relay 144 is drawn over against post 149, by the energizing of the coil of relay 144, a path is opened for the next current to operate. This next current emanates from battery 520 which is on the metallic circuit (i. e. using both line wires 200 and 300). Upon depressing key 514 current flows from the battery 520 over key contacts 515, 514, 90 wires 522—501 to line connection 208 into line wire 200, flowing along the line wire and its station connections to lever 105 of the auxiliary apparatus station #1, over such lever 105 to contact 114, wire 95 245, to lever 141, along such lever to contact post 142, and from thence over wire 261 to the coil 119 of switch (S. R.—H.) through that coil over wire 267, to contact 132 of relay 127, across the 100 armature 131 to contact 134, over wire 263, to contact 149 of relay 144, across its armature 146 to line wire connection 301 and via wires 45—55—308—307—83—84 back over line wire 300 to the central station, in over wire 312 to branch 525 across switch contacts 497, 501, over wire 521, back to battery 520, thus completing the circuit. When the current from the battery 520 was passing through the main coil 119 of switch (S. R.—H.) the magnet bar 120 of that switch was 110 thrown over by the action of this current into contact with pole pieces of relay 128 that holds the bar in its shifted position by the local current that is switched from the winding of relay 130 into the winding of relay 128, such local current flowing over wires 322—321 to lever 104 (which has been released by the deenergizing of the magnet 101 due to the breaking of the circuit between the lever 120 and the core contact of relay 130 when 120 left that place), and from thence to contact 116 with which the lever is engaged upon deenergizing of the magnet 101, and over wire 292, back to battery 97. The breaking of the circuit between the lever 120 of switch (S. R.—H.) and the contact of the core of relay 130, not only broke the circuit for magnet 101 but it also broke the circuit of magnet 102. The 120 115 125 130

deenergization of magnets 101 and 102 would allow the levers 103 and 105 to move over and break the circuit with contacts 117 and 114 respectively. The lever 105 is, however, prevented from dropping over to break the circuit at contact 114 by reason of the energization of the coil of relay 111 by the constant current from battery 510 of the central station that flows over line wire 200 with ground return. This completes a half setting of the auxiliary apparatus and prepares it for the testing processes or the complete setting for telephonic communication between two parties, as will be later explained.

The apparatus having been half set as above described, the testing process is conducted as follows: The switch 500 at the central station is thrown over so that its levers engages the contacts 496 and 502 respectively and disengage the contacts 501 and 499, thereby throwing the bell 504 and sounder 503 into position for action. As the current from battery 510 is still flowing and when switch 508 is closed, both currents *i. e.* those from battery 510 and 520 flow to the prepared station and return through the sounder 503 and bell 504. If both the sounder and the bell operate at the same time, it indicates that both lines 200 and 300, and the earth connections are so far in order. The current from battery 520 upon closing of the key 514 has, however, at the subscriber's station, taken another path skipping the big coil 119 of switch (S. R.—H.) to return with greater force. This other path is from contact 114, over wire 245, to relay lever 141, which has been drawn over into contact with contact 221 by the energization of relay 128 when armature 120 was moved into engagement with the core contact under the influence of the action of the coil 119 as hereinbefore described. The current flows from lever 141 to contact 221 and from thence over wire 222 to contact 223, and across the insulated contact 224 of lever 145 (the latter being held over by the energized coil of relay 144) and from the contact 224 of lever 145 over contact 148 and connection 264 to wire 301 and return via connections 45—55—308—307—83—84 over line wire 300, back to central station in on wire 312, along wire 525, to lever 497, over lever to contact 496, through sounder 503 and from there over wires 507 and 521 to return to battery 520. The current from neither of the batteries 520 or 510 can flow to any stations beyond the first one being tested for the reason that so long as the current from the battery 510 is flowing through sustaining relay 111 of the station being tested the lever 225 of that relay is drawn over to open the circuit at contact 226, so that the circuit that would otherwise be formed from contact 114 via wire 245, armature 138, con-

tact 139, wire 244, contact 226, armature lever 225, and wire 243 to line connection 202, will be broken at the relay 111.

The foregoing describes the way in which the line connections between a station and the central station can be tested, as well as the ground connections.

To set the station for telephonic communication.—For telephone communication it is necessary to set the other magnet bar 121. This is done by using a current from the battery 530 at the central station via line 300 and ground return. The current from battery 530, upon depression of key 524 flows over the key into line wire connection 525 and out over line wire 300 to the station that has been half set, as before described, for testing purposes. The return circuit at the central station is from the ground over wires 541, 528 to battery 530. The current from battery 530 that flows over wire 300 enters the particular station over wires 84—83—307—308—55—45—301 and passes to the lever 146 of relay 144 (which is still energized by the current from battery 510 as hereinbefore described), across that lever to contact 149 and from that contact, by wire 263, the current passes to contact 134 then over lever 131 to contact 132. From contact 132 the current flows over connection 267, through coil 119 of switch (S. R.—H.) and from thence over wire 261 to contact 147, over lever 145, wires 249 and 250, to telephone studs 165, 164, and from thence to ground and return to central station. The energizing of the winding 119 of switch (S. R. H.) by this latter current from battery 530 results in the magnet bar or lever 121, being drawn over to disengage the core contact of resting relay 129 and engage the core of holding relay 127 and at the same time close the circuit at contact 126. The relay, 127 is immediately energized by a local current to keep the magnet lever 121 over in that position. The local circuit thus established is from battery 97 to lever 121, through 326 and coil of relay 127, wires 325, 324, 321, lever 104, contact 116 and wires 292 and 291 back to battery 97. At the moment that the bar 121 was drawn over into contact with the core contact of relay 127, and that relay became energized, by the local current mentioned, the circuit through the coil of resting relay 129 is thereby broken, whereupon the lever 136 is thrown back into engagement with the contact 137 and this closes a local circuit of which the battery 98 is the energizing source. In this local circuit the current flows over wire 296 via armature lever 136, contact 137 over wire 319, through the coil of holding relay magnet 99 and from thence the current returns to battery 98 via wire 320. Relay 99 is now energized by the current from local battery 98 which energizing current flows constantly

until the apparatus is reset, thereby sustaining the lever 105 in the position shown in station (Fig. 4) namely, its normal position. The main line current from battery 510 is now cut off at the central station switch 508, and telephonic communication can be effected between the central station operator and the station whose apparatus has been set as described or between say two stations that have been set in the manner above described. It will be noticed that there is now a through line through the set station from the line wire connection 201 to the line wire connection 202. The passage is from connection 201 to lever 105, thence to contact post 114, through wires 245 to armature lever 138 to contact 140 and from thence over wires 332 and 269 (S. R.—H.) contact 123; from contact 123 to contact 126 and from thence over wire 268 to line wire connection 202. The reason why a gap is provided between the line wire connections 301—302 at contact 150, is that the battery 530 and key 524 (circuit line 300 and ground return) are not used alone for the setting of the magnet bar 120 of switch (S. R.—H.) but such battery is also used for throwing the constant current battery 391 at the interchanging station into circuit; therefore in order to be able to use the battery 530 for both purposes, it is necessary to break the circuit between line wire connection 301 and 302 through the medium of the relay armature 146 and contact 150 so that under normal conditions the circuit will be closed and will be opened at the moment the current from battery 510 is brought into play to energize the relay 144. Supposing now that a station (say station 1) has been set for telephonic communication. The parts will be in the position indicated in Fig. 4, excepting that the armature 121 of magnet 127 and armature lever 131 of switch (S. R. H.) are however thrown over to the opposite position the magnet 129 will be deenergized and its armature 136 will be resting against the stop 137. Suppose that the first station (station #1) wants to speak to another station (station #30) in that event all of the intermediate stations (stations #2 to #29 inclusive) will have to be locked out of connection, and this is done in the same way hereinbefore described for the first part of the action of setting the station for testing purposes, viz: The switch 508 is closed and the current from battery 510 is kept flowing constantly (via line 200 and ground return) and this act is followed immediately by the current from battery 520 upon depression of the key 514 (circuit lines 200 and 300). The current from battery 510 and from battery 520 flowing out from the station, over line wire 200 through station #1, via wires 41, 42, 204, 205, 43, 44, 201, armature lever 105, wire 245, lever 138, contact 140, wires 332,

269, 268 and wires 202, 203, 49—48, over line 200, etc., to the armature 105 of the second station (station #2) and over such armature to the contact 114. At the contact 114, the two currents divide, that from the battery 510 flowing through the coil of relay 111, over wires 246, 247, relay armature 108 and contact 109, wire 248, winding of relay 144 (S. R. H.) wire 249, wire 250, across telephone contacts 165, 164 to ground and return, while the current from the battery 520 flows from post 114 over wire 245, across armature 141 and through wire 261 to the coil 119 of switch (S. R. H.) (station #2), through that coil and over wire 267, lever 131, and over wire 263 to contact 149, over armature 146 (relay 144 being energized by the current from battery 510), back into return line wire connection 301 and over wires 45—55—308—307—83—84 line 300, to line 85 wire connection 52 of station #1, through the connections 52, 53, 306, 146, 305, 151, 155, 304, 303, 156, 152, 302, 150, armature 146 to relay 144 (which had deenergized by breaking its circuit at 108, 109 when relay 99 was energized by the last act of setting station No. 1) then through 301, 45, 55, 308, 307, 83, 84, 303 back to central.

The current that has passed through winding 119 of switch relay (S. R.—H.), (station #2) has thereby thrown the magnet bar 120 of that switch-relay over against the armature of the holding relay 128 to which it is held until released in a manner described hereinafter. The shifting of the magnet bar 120 of switch-relay S. R.—H. (station #2) broke the circuit through the coils of bridging relays 102 and 101, thus releasing the three armatures 103, 104 and 105, the armatures 103 and 104 immediately dropping over to the position opposite to that shown in Fig. 4, and as no further operation is needed at the intermediate station (station #2) the switch 508 at the central station is opened, thereby deenergizing the holding relay 111 and permitting the armature 105 also to drop over and close the main line circuit with contact 115 at station #2. The dropping over of the armature 105 also results in the deenergization of the relay 144 and closes the main line circuit connections 301 and 302 thus leaving a clear main line circuit through station #2 to connect station #1 with the next following station. All of the stations following station #2, excepting the station with which it is desired to effect telephonic communication (station 30) are locked out progressively in the same manner by the central station operator until the desired station (station 30) is in free communication. Station #30 having been operatively reached, the central station operator again closes the switch 508 and depresses the key 514, where-by the current from batteries 510 and 520 125 130

now flow over the main line wires, and through the main line connections of the locked out stations (intermediate stations) to the lever 105 of station #30, which station is now set by the central station operator in the same way as hereinbefore described with relation to the setting of station #1 for telephonic purposes. As soon as station 30 has been set the central station 10 operator rings his telephonic bell ringer 478. This causes the bells 168 of the telephones of the parties at stations #1 and #30 to be rung at the same time and by unhooking the receivers 160 the parties at the two stations 15 are now in connection with each other. The telephone circuit is now limited to a connection between the two connected premises, stations #1 and #30. The path open for the telephone current from station #30 20 to station #1 is from the contact post 166 (station #30) via wires 270, 332, armature 138, wire 245, contact 114, lever 105, line wire connection 201, and from thence to line 200, over line wire 200 to station #1, 25 where it comes in over line wire connections 48-49-203-202 and passes via wire 268, contact 126 (S. R. H.), contact 123, wires 269, 270 to telephone contact stud 166 of station #1. It should be understood that 30 the usual local battery talking circuit (not shown) would be used in practice to furnish current for talking purposes. The operating party at station #1 can there depress the interrupting button 331 so as to disconnect 35 the central station and prevent the central station operator from over-hearing the conversation.

It should be noted that my system is not intended primarily for telephone communication, for if that were the case, automatic selecting instruments should be provided for quick connection purposes.

Any station or subscriber wishing to communicate with the central office to order a 45 connection with some other party calls the central station operator up but at the time he gives the telephone ring, he also depresses the key 152, holding it depressed while communicating with the central office. 50 The depression of the key 152 breaks the line wire connection between sections 302 and 303 and connects the telephone of that station with line wire 300 (via wires 302 and 303), and ground return, for a direct connection 55 with the central office. The depression of the key 152 interrupts the normal constant current that is in the main line circuit and line 300 is broken at the place of interruption, so that there is no way open 60 for the magnetic calling current to go through the central station's polarized relay and out on line 300. The only path for the current at the central station is now through the central station's telephone, the way designated 65 for it. When the central station

calls any station up to speak with it, it must be done through the setting of the stations, nevertheless, if the central station operator only wishes to speak to one party, the setting of the magnet bar 120 of switch-relay (S. R.-H.-) of the particular station, is sufficient. 70

Resetting of the auxiliary apparatus after testing or telephone communication.—After the conversation between the two parties is 75 completed, or after testing the lines, the proceeding of resetting the instruments takes place. This is accomplished by the central station operator pressing the key 535, opening the circuit at switch 508 so as to disconnect battery 510. The current flowing, upon closing of the key 535 emanates from the battery 540 and flows over line 300 to the armature lever 146 (S. R.-H.-) of all of the locked out stations and both of the stations set for telephone communication. 80

From the lever 146 the current flows to post 150 and from thence by a wire 262 to contact post 125 of switch-relay (S. R.-H.-) over magnet bar 120 of the same through core of 85 relay 128 and over wire 276 to the one winding of the coil of relay 110 and from thence over wire 275 and wire 201, etc., to line wire 200 and return to battery 540 via connection 208, 539 at the central station. As soon as 90 this current is established the coil of relay 110 is energized and attracts the armature lever 104 (which had been resting against contact posts 116 since the magnet bar 120 was thrown into contact with the core of 95 relay 128). The lever 104 thus is brought out of engagement with the contact post 116 and the local circuit through relay 128 is broken thereby releasing the magnet bar 120 of switch relay (S. R.-H.-) and permitting 100 it to drop back into its normal position into contact with the core of relay 130. This breaking of the local circuit at contact 116 also results in the deenergization of relay 127 which permits the magnet bar 121 to 105 reassume its normal position in contact with the core of relay 129 which thereupon becomes reenergized. The restoration of the magnet bars 120 and 121 of switch relay (S. R. H.) also results in breaking the local 110 circuit that includes the relay 99 at the contact 137 which releases the armature 108 to reestablish the circuit connection between the wires 247 and 248; it also results in the reenergization of the resting relay 130 and 115 the deenergization of the relay 128 with the consequent reenergization of relays 101 and 102 which thereby attract the armature levers 103, 104 and 105 respectively into 120 their normal positions. By closing the key 535 all of the stations are simultaneously 125 reset.

It should be understood that when the main line circuit is cut at any of the stations the circuit of battery 391 (interchanging 130

apparatus, Fig. 5) is broken and the magnet of relay 367 (S. R. K.) becomes deenergized thereby releasing its armatures 382 and 383. This breaks the circuit between 5 the members 383 and 385, so that after the apparatus of the subscribers' stations becomes reset, the normal main line current will yet be cut off, and in order to reset the battery 391 into action the central station 10 operator first closes switch 516 which sends out a current over line 300 with ground return, to pass current through relay 242 (S. R. K.) via wire 412, armature 387, wire 411 and wire 409 to close the local circuit 15 from battery 391 through coil 367 over wire 410 and thereby draw over the armatures 383 which then permits the current from battery 391 to flow in its normal path and energize the magnet 367 to hold over the 20 armatures 382 and 383. The central station operator then opens switch 516.

The disconnecting of a disabled station and stations beyond the same from the circuit of central station.—Suppose for the 25 sake of an example, that there are one hundred stations in each section, and it has been found necessary to eliminate station 86 of section #1, because of some trouble, such as a serious conflagration. In order to cut out 30 station 86 without rendering stations 87 to 100 inclusive inoperative by reason of such elimination of station 86, I have made provision whereby all stations beyond the station to be eliminated may be cut over into 35 the circuit of section #2 of the installation, and in order to accomplish this, it is necessary to first lock out all of the stations up to station #84. The locking out act is accomplished in the manner hereinbefore described. After all of the stations up to station #84 are locked out, station #85 is set 40 as if for a telephonic connection in the manner hereinbefore described with relation to the apparatus of station #1. This having 45 been done, it is still necessary to effect an additional setting of the apparatus of station #85, and this is accomplished in the manner now to be described. Assume station #85 to have been set with the parts in 50 position for telephonic communication, when the magnet bar 121 of switch (S. R. H.) of the last station (the 85th station) of the first section of installation has been set, the 55 local current passing through the coil of relay 127 has attracted lever 131 to close the circuit between contacts 133 and 135. This opens a new path for a current sent out by battery 530 upon closing key 524 via line 300 and ground return. As there is at this 60 time a path open for this current at the extreme interchanging station, some means must be provided to prevent the current flowing farther than to station #85 (the path referred to being into interchanging apparatus line wire connection 309 'p' wire

412, through wires 411, 409,—S. R. K.—to ground). As all of the intermediate stations (1 to 84) are now locked out of connection the auxiliary constant current from battery 510, when the circuit of that battery 70 is closed (flows directly over the bridging arrangement via the lever 105 (which in all of these locked out stations is resting on posts 115, the same as the other levers 103 and 104 are resting on post 86 and the post 75 116 respectively)—the current continuing over contact post 115 and out over line wire connections 202, 203, 49, 48 and main line wire 200, through the various stations up to the 85th station. This current cannot flow 80 through any of the intermediate locked out stations over connection 243, 244 for the reason that the circuit is open at contact 139 in all of the intermediate stations when they are locked out.

When the current from battery 510 reaches the 85th station, it passes through the coil of relay 144 to earth return, causing the lever 146 to be attracted to open the circuit of line 300 between the line connections 90 301—302, so that the next current impelled, the current from battery 530, upon depression of key 524 (circuit line 300 and ground return) is compelled to flow over the connection 264, 266, to contact 135, across armature 131 to contact 133 and from thence through wire 256 through coils 89 and 88 of switch F to wire 255, and via wire 253 to ground return over telephone lever contacts 165, 164, etc. The direction of the current 95 that passes through these coils in order to uphold momentarily the armatures 90 and 92 against post 94, is such that it would attract armature 70 of switch F into resting place, but as it is already in that position, it 100 will not be shifted by the passing impulses, having that direction. The current which passes through coils 89—88 via line 300—g does not throw over switch F in station #85 from its normal position shown in Fig. 4, as such switch must remain in its normal position at station #85, so long as that station 105 remains on section #1. The next operation is to throw switch G to cut in the auxiliary terminal batteries 95—96. While current is 110 flowing through coils 89—88, from battery 530, the operator closes switch 508, to cause current to flow from battery 510 via line 200—g. Current from battery 510 enters the auxiliary apparatus of station #85 via line connection 201, and passes via lever 105, through coil 111, over wire 246, attracted armature 92, contact 94, via wire 277, contacts 73—72, wire 230, one winding of coils 67—66, wire 285, contacts 69—76, wire 278, a part of wire 255, wires 253, 250, contacts 165, 163, 164, wires 251, 252, to ground and return to central station. This energization 115 of magnets 67—66 causes the armature 54 to rock over to open the circuit between con- 120 125 130

- tacts 58—59, 69—76, 72—73, and 64—65, and simultaneously closes the circuit between the other sets of contacts. The energization of magnet 66 also opens the circuit between armature 80 and contact 81. The central station operator now opens the switch keys 524 and 508 which causes a deenergization of the coils 89—88 and 67—66, and permits the armatures 90, 92 and 80 to drop.
- 5 It will be observed that at station #85 the switch F is normal while the switch G is thrown over. Throwing over the switch G brings the auxiliary batteries 95, 96 into action. As the station beyond #85 is disabled, 10 the battery 96 is idle while the battery 95 furnishes the normal main line current upon re-setting the bridging relays E and the switch relay H, which latter acts are accomplished by the operator at the central station depressing the key 535 to bring the battery 540 (circuit lines 300—200) into action. This causes current to flow into the auxiliary apparatus of station #85 via line connection 301, armature 146, contact 150, wire 15 262, contacts 125—124, lever 120, core of relay 128, wire 276, one winding of relay coil 110, wire 275, armature 105, line connection 201, etc., back to central station. This restores the lever 104 to normal and breaks the local 20 circuit through relays 128 and 127 at contact 116 thereby permitting levers 120—121 to resume their normal positions and consequently restore the levers 141, 138, 136, 131 to their normal positions. All of the stations up to station #85 are now reset to 25 their normal position (in the manner hereinbefore described), the battery 95 now functioning as the normal main line current producer until the break at station #86 can be repaired. Essentially the same operation 30 must now occur in section #2 of the installation so as to cut over stations #87 *et seq.* into the circuit of section #2.
- The manner of operatively connecting the unimpaired stations disconnected from one section into the circuit of another section.*—
- 35 The next move is to connect station #87 *et seq.* of section #1 onto the end of section #2 through the medium of the interchanging apparatus at station #2 and establishing a bridging connection between section #2 and section #1, and then lock out all of the last stations of section #1 excepting that following the disabled station, namely 40 excepting station #87, and set station #87 as an end station. It will be understood that the terminal lines of two sections of installation are connected by an interchanging apparatus through interchanging station.
- 45 All of the stations of section #2 of the installation are locked out by the central station operator manipulating the central station apparatus that corresponds with section #2 in a manner similar to that described 45 with relation to section #1. After all of the
- stations of section #2 have been locked out, it is necessary to set the interchanging apparatus of the interchanging station before it is possible to lock out the stations of section #1, that are located beyond the breach. 50 The central station operator now closes the switch 508 of section #2 of the central station apparatus, to cause a current to flow from battery 510 (via line 200 and ground). This current flows through the various 55 locked out stations of section #2, and enters the interchanging station (Fig. 5) over line connection 207, the current flowing to lever 342, and from thence to contact 349. From contact 349 the path of the current is as 60 follows: Through coil 336, over wire 416, through one winding of relay 367 (S. R. L.), over wire 398, through one winding of coil of holding relay 366, and over wire 399 to ground and return. As this current is kept 65 flowing until the setting of the interchanging station has been completed, and as levers 382 and 383 of relay 367 (S. R. L.) are thrown over against the respective contacts 384—385, the circuits are closed between 70 said levers and the respective contacts, and as lever 377 of relay 366 is held in contact with post 379, a path has now been opened 75 for another current which emanates from battery 520 whose circuit is line 200 with 80 return via line 300. This current flows (upon depressing the key 514) over that key and out over line wire 200 to the interchanging station, passing over the main line connection of the locked out stations of section #2, 85 and entering the interchanging station over line wire connection 207. The current flows over connection 207 to lever 342 and from thence to contact 349. From contact 349 90 the current passes via wire 415 to contact 381 of relay 366, (S. R. L.) over the armature 377 thereof to contact 379 and from thence it flows over wire 401 through the coil 359 of switch (S. R. L.) and from thence over wire 394 to the contact post 371 95 of relay 364 over armature 369 to contact 370 and from thence via wire 418 to line wire connection 310, up over that connection to post 386 and from thence via magnet bar 360 and line wire connection 311 to line wire 100 300 and return to central station. This current in passing through the coil 359 has energized the same and has thereby drawn over both magnet bars 360 and 361 of (S. R. L.) 105 to disengage respectively the contacts 386 110 and core of relay 365 and simultaneously engage respectively contacts 390, pole piece of relay 364, and the pole piece of relay 366, 115 and these levers are now kept in this position by the local currents which pass through the relays 364 and 366 respectively, such currents emanating from battery 425. Resting relay 365 has now become deenergized and released its armature 375, whereby it may 120 drop against the contact 376 thereby closing 125 130

the local circuit at this place and permitting current to flow from battery 392 via wires 437, 439, to coil of bridging relay 340 and return to battery via wire 441, thus energizing the relay 340 to hold the bar 342 in its normal position, the levers 343 and 344 having now fallen back to break with contact 350 caused by the cessation of the energizing current that flows through the relay 338 and 339 respectively, due to the shifting of the magnet bar 361 (S. R. L.) out of engagement with the core of relay 365. Lever 369 of relay 364 (S. R. L.) has been attracted over against the contacts 372 and 373 respectively, thereby forming a path for the resetting current when it is desired to have this station put in normal position. Right here it should be mentioned that the switch relay section (S. R. K.) of the interchanging apparatus is only operated by currents coming in from central station over section #1, of the installation, while switch relay (S. R. L.) is operated only by the currents coming in from the central station via section #2 of the installation. It should be also noted that the operation of switch relays (S. R. K.) and switches S. R. H. is substantially the same as the operation of switch relays S. R. L. and switches S. R. I. when it is desired to cut over stations from section #2 into section #1, and therefore I shall not describe this reverse operation as I believe it will be clear to those skilled in the art from what has gone before. The switch 508 at the central station (section #2 of the apparatus) is now opened to break the circuit of battery 510, which causes the deenergization of relays 367 (S. R. L.) and 336 (B. R. J.). The armature levers 382 and 383 of relay 367 are thereby released, as is also armature 347 of relay 336 (B. R. J.). It should be understood at this time lever 377 has not yet been released but remains in contact with contacts 379 and 381 of relay 366 (S. R. L.) which is energized by the local circuit that flows through the magnet bar 361 and said lever 377 remains in that position until all of the instruments are reset.

50 The foregoing establishes the connections for the continuation of the main line circuit through lines 200 and 300 of section #2, over into the disconnected portion of section #1, through the interchanging apparatus at the interchange station. The current from battery 510 of the central station apparatus that is flowing in section #2 on depressing switch 508 comes in over line 200 (interchanging station), flowing over connection 207 to the connection with wire 424 to armature 347, and over to contact 351; from thence through wire 421 to contact 354 across armature 345 (which is attracted by the locally energized coil 340) over wires 420—419

to armature 348, across that armature to contact 353 and through connection 423 to line wire connection 206 and thence on to the stations of section #1 which are to be locked out down to the station adjacent to the injured one, viz:—stations #100 to #87 inclusive. The circuit through line 300 is as follows:—(returning from the last station of section #1) over line wire connection 309 to the core of relay 364 (S. R. L.) to magnet bar 360 and back to central station, section #2, via line wire connection 311 and line wire 300. The path of the currents over section #2 of the installation from central being now clear through the interchanging station into the line wires of the disconnected end stations of section #1, all of the stations of section #1 down to but not including station #87, are locked out through the operation of the switches S. R. I. in these stations by the currents over section #2 in a manner similar to the operation of the switches S. R. H. by the currents from section #1, as hereinbefore described and therefore a repetition of the locking out will not be, it is thought, necessary. Stations #100 to #88 of section #1 of the installation having been locked out, it is now necessary to set station #87 as station #85 was set viz:—as an end station. The first current impelled to station #87 is that of battery 510 (circuit line 200 and ground return), switch 508 is thrown in at the central station and the current flows over line 200 through the interchanging station to station #87, entering over line wire connection 48, 49, 203 and flowing over a portion of wire 273 and over wire 279 to lever 103, and from thence to contact 117 and through coil of relay 118 over wires 259, armature 90, contact 91, wire 258, lever 106, contact 107, wire 254, through winding of relay 144, (S. R. I.) (energizing the same) and via wires 253—250, telephone contacts 165—163—164 and wires 251—252, to ground and return. This current is now followed by the current from battery (circuit lines 200 and 300) upon depressing key 514. The current flows into station #87 over line wire 48, 49, 203 and passes over a portion of wire 273 and wire 279, to lever 103 and contact 117, and from thence current flows through wire 260 to armature 141 of relay 128 (S. R. I.) and from thence via wire 261 through coil 119 (S. R. I.) flowing via wire 267 across armature 131 to contact 134, and via wire 263 to contact 149. As armature 146 is held over to contact 149 by the current from battery 510 (switch 508 being kept closed), the current from contact 149 will flow over armature 146 and return to central station, via section #2 of the installation and line wire connections 306, 53—52. The energizing of the coil 119 of

switch S. R. I. results in magnet bar 120 of that switch being thrown over into contact with the core of relay 128 and also into contact with contact 125, thereby establishing the energization of relay 128 by the local current from battery 97 and breaking the circuit between armature 141 and contact 142, and make it with contact 221. The operator at the central station next depresses key 524, thereby setting up a current from battery 530, whose circuit is line 300 and ground return, current flowing over line 300 to station #87 and entering the same over connections 52, 53, 306, flowing to armature lever 146 and from thence to contact 149, passing from that contact through wire 263 and 267 to the coil 119 of S. R. I. through the same via a portion of wire 261 to contact 147 and across that contact over armature 145, through wire 253, wire 250, telephone contacts 165, 163, 164, wires 251, 252 to ground return. The first of the above currents, namely, that from battery 520, moved magnet bar 120 of switch (S. R. I.) over, as before stated, while the second of the above currents, namely that from battery 530 drew magnet bar 121 of that switch over against the armature of relay 127 and broke the circuit through relay 129, thereby releasing its armature 136. When bar 121 moved over to contact the core of relay 127, that relay became energized by the local circuit, and contacts 123—126 became closed, while relay 127 moved its armature 131 into engagement with contacts 133—135, respectively.

Inasmuch as station #87 is to be an end station or section #2, it is necessary to throw over both switches F and G, to bring the auxiliary main line terminal battery 96 into action, and also to switch over the line terminal connections for the fire and burglar alarm apparatus, so as to bring them in proper connection in the main line circuit to send out their current impulses over section #2. The central station operator now closes key 533 to send out a current from battery 542 via ground and line 300 return. The current enters station #87 at wire 252 and passes via wire 251, telephone contacts 164—163—165, wire 250, a portion of wire 253, over wire 255, through coils 88—89 of switch F, over a portion of wire 256, over wire 257 to contact 135 of (S. R. I.) armature 131 to contact 133, over wire 235 to line wire connection 306, over wires 53—52, to line wire 300 and return to central station. The energizing of coils 88—89 rocks over armature 70 to reverse the line terminal connections between the terminal posts 1 to 12, inclusive. The energizing of coils 88—89 also raises armatures 90 and 92 into contact with plate 94. The operator, while holding key 533 depressed, now closes switch 508 to

send out a current from central station battery 510, via line 200 and ground return. This current enters the auxiliary apparatus of station #87 over wires 48, 42, 204, 205, 43, 49, 203, passes via a portion of wire 273, wire 279 to lever 103. This lever rests against contact 117 by virtue of the energization of relay 100 by the circuit from battery 98 over lever 136 (S. R. I.) which has been retracted by the deenergization of relay 129. The current from lever 103 passes to contact 117 and through coil 118 over wire 259 to armature 90, contact 94 over wire 277, contacts 73—72, coils 67—66, wire 285, contacts 69—76, wire 278, a portion of wire 255, a portion of wire 253, wire 250, telephone contacts 165, 163, 164, wires 251, 252 to ground and return to central station, thus throwing over armature 54 by energizing coils 67—66, thereby closing the circuit between contacts 60—61, 74—75, 62—63, and 85 opening the circuits between the other sets of contacts and at the same time opening the circuit between armature 80 and contact 81. This act brings battery 96 into circuit with the terminals of the line wires of station #87 that run in from the direction of section #2, as will be clearly understood by reference to the drawing. This operation establishes section #1, station #87 as the end station for section #2. The central station operator now opens the keys 508 and 533 and depresses key 535 to send out a current over section #2 from battery 540 to reset all of the stations now on section #2 excepting the interchanging station, as before described with relation to the stations of section #1. It should be stated that all of the switches E, F, but not the switches G, of stations #88 to #100 inclusive of section #2, are thrown over so as to bring the fire and burglar alarm mechanism line terminal connections into proper relation with the main lines to send out their signals over section #2, and the throwing of the switches F in stations #88 to #100 inclusive of section #1 is accomplished by the central station operator acting over section #2, by setting the stations for telephonic communication and then sending out a current from battery 542 via ground and wire 300 return. This current enters the stations, as hereinbefore described, with relation to the throwing over of switch F in station #87 and a further description thereof is at this place thought to be unnecessary. It will now be seen that there is a normal current flowing from battery 96, section #1, station #87 through the remaining stations of section #1, via the interchanging station and all of the stations of section #2 to the central station, such battery now taking the place of the normal battery 392 of the interchanging apparatus, current from battery

95 of station #85 is acting from the stations that remain on section #1. At this time there are 85 stations connected in section #1 of the installation and 114 connected on section #2.

The apparatus of interchanging station D and the switches F and G of station #87 remain in this position until the interruption at station #86 has been repaired. The next operation is for the central station operator, operating over section #2 to reset the stations of section #2 and the connected stations of section #1, and this is accomplished in the manner already described with relation to the resetting of the first 85 stations.

Restoring the two sections to their original connections.—Now let us suppose that the imaginary interruption at station #86 of section #1 has been repaired, and it is desired to re-connect that and the succeeding stations of section #1 with the central station via section #1, line wires and operationally dis-connect them from section #2.

To do this it is necessary to again lock out all of the stations from both sides up to stations #85 and #87, section #1, and to reset those stations to their normal positions. Station #85 is now set as for a telephonic communication as hereinbefore described. The central station operator operating over section #1, closes switch 516, thus sending out a current through the line 300 to station #85 with return via ground. The current enters the auxiliary apparatus of station #85 over line wire connection 301 and passes via wires 264—266 to contact 135 (S. R. H.), flowing over armature 131 to contact 133, through wire 256, coils 89—88, wires 255—253, 250, 251, 252, to ground and return. This energizes magnet coils 89—88, (when armature 70 of switch F at station #85, section #1 is in normal position (see Fig. 4) it will not be effected) to close the contacts 90—92. While maintaining this circuit closed to hold up armatures 90—92, the central station operator momentarily closes switch 508 to set up current from battery 510 via line 200 and ground. This current enters the auxiliary apparatus of station #85, section #1, over line connection 201, passes over lever 105 to contact 114, thence to magnet 111, over wire 246 to lever 92, across to contact 94, over wire 277, across contacts 75—74, through wire 78, over contact 81 and polarized armature 80, over wire 82 through the second winding of armature coils 66—67, over wire 287, contacts 68—77, wires 278, 255, 253, 250, 251, 252 to ground and return. The central station operator now opens switches 516 and 508 (if the latter has not already been opened, since a momentary closing of the same is all that is necessary) thus permitting armatures 90—92 to drop. Key 535 is now depressed, at the

central station, to send out a current having as its circuit lines 300—200, to energize the magnets 110 at all stations on section #1 up to and including station #85 which thereby resets such stations to the normal position, as heretofore described. Having reset the stations of section #1 up and including station #85, the same action must now occur over section #2 for station #87 of section #1, that is to say,—the switches F and G of that station must be restored to their normal positions and the station reset by currents acting over section #2. All stations of section #2 and the 13 stations from station #100 to station #86 of section #1 inclusive are first locked out by manipulation from the central office, as hereinbefore described, via section #2 to prevent the current from battery 510 of section #2 taking its path through any of these stations. Switches F and G of station #87 both require resetting to their normal position, so it is necessary to first send out a current from central station via section #2, whose circuit is line 300 and ground return, and follow that current immediately by a current whose circuit is line 200 and ground in the same manner as hereinbefore described for station #85. A repetition of the description of this operation is thought unnecessary. The stations of section #1, between the interchanging station and station #86, are then reset by current from battery 540, over section #2, in a manner, as hereinbefore described with relation of section #1, 100

The resetting of the interchanging station.—The next step in the restoration of the several sections to their normal relationships is to reset the apparatus of the interchanging station, and this is accomplished as follows: The switch 516, at the central station, is closed and current comes into the interchanging station, via section #2 of the installation over line wire connection 311. From thence it flows to lever 360 thence over that lever to contact post 238, through relay 242, and passes to ground over wire 409 and return to central station where it enters over wire 541 and flows back to battery 530, via switch contact 517. This current, which is maintained until the resetting current has acted, energizes the relay 242 and draws over the armature 239, thereby establishing a local circuit from battery 392. The local circuit current flows from battery 392 over wire 406, through one winding of coil 367 (S. R. L.), through that coil and out over wire 410 to contact 240, from thence over armature 239 and wire 241 to line wire connection 310 and return to battery via wire 408. This local current energizes the relay 367 and draws over the armatures 382—383 to close the path for the local circuit.

If only the interchanging station is to be 130

reset, current is sent out from the central station battery 520 over line 200 and return via line 300. This current which is set up, upon depressing key 514, enters interchanging station over line wire connection 207 and passes over lever 342 to contact 349, from which it flows through wires 415 and 396 to lever 382 across that lever to contact 384 over wire 395, contact 372, lever 369, contact 373, wire 393, contact 374, lever 361, core of relay 366, wire 403, through one of the windings of relay 358, over wire 405 to line wire connection 311 and return to central station. This energizes relay 358 which thereby throws over armature 343 to break the local circuit at contact 352 and thereby deenergizes relays 366 and 364 (S. R. L.), which permits the armature levers 360—361 to thereby drop back to their normal positions, and at the same time establish a local circuit through coils 338—339 to hold levers 342—343—344 (B. R. J.) to their normal positions. The resetting of the levers 360—361 reestablishes the normal circuit connection. When the central station operator releases key 514 the main line circuit from battery 392 is established through relay 367 to hold the armatures 382—383 in position. When the lever 360 (S. R. L.) was in contact with the core of holding relay 364 and the circuit from battery 530 was established the current not only passed through coil 242 in S. R. L. but it also passed over line wire connection 309, to wire 412 (S. R. K.) over that wire, armature 387, contact 388, wire 411, through coil 242 (S. R. K.) to ground over wire 409 to close the local circuit from battery 391 through one winding of coil 367 at contact 240; whereby to establish the normal energizing current of battery 391 over section #1. The central station operator now opens switch 516 which leaves the interchanging station apparatus in its normal position.

After the interchanging apparatus has been reset the 100 stations of section #2 of the installation are reset by pressing key 535 (central station apparatus, section #2) to cause the battery 540 to send out the resetting current over line 300 and 200 return. This current enters all of the one hundred stations of section #2 over line wire connection 301 and passes to contact 150 (S. R. H.), flowing over wire 262 to contact 125, lever 120, core of relay 128, flowing over wire 276, through one coil of relay 110 (B. R. E.) and from thence the current flows over wire 275 to line wire connection 201 and return to central station. The energization of relay 110 draws over the lever 104 which breaks the local circuit through relay 128 and permits lever 120 to drop thereby closing local circuit through relay 130 and consequently energizing holding re-

lays 101—102 to thereby draw over the levers 103—105 to their normal positions. The resetting of the stations has broken the main line battery circuit connections at the interchanging station so it is necessary to reset the battery 392 into action. In order to reset the battery 392 into action, the signal station operator closes switch 516, which sends out a current over line 300 with ground and return to pass current over relay 242 (S. R. L.) via wire 236—237 from contact 234 through relay 242 and wire 409 to ground and return. This closes the local circuit of battery 392 through coil 367 via armature 239 and contact 240. This local circuit draws over the armatures 382—383 which reestablishes the main line connection and allows the battery current from battery 392 to divide after it passes through the relay magnet 367 one portion flowing over wire 410, as before, and the other over wire 397 etc. to line. The operator then opens the switch 516 which leaves the battery 392 to act as the normal energizing battery. Any break in the lines will result in a deenergization of relays 367 of the interchanging station and will require their resetting, as before described, in order to restore the batteries 391—392 into operation. The resetting current, which establishes the constant current on the main line, sustains the lever 241 of relay 242 of the interchanging station, so long only as the current flows through that relay (242) whereafter it falls back, leaving the full potence of the constant current to flow out on the line. When any operation of the lines is required, the normal battery current is released or operatively disconnected by the central station operator opening the switch 543 and is reestablished when desired by closing switch 516 and depressing key 535 for an instant.

From the foregoing description taken in connection with the accompanying drawings, it will be noticed that my improved system provides not only for the sending in of fire and burglar signals from protected premises but it provides a means under control of the central station operator for testing the lines so that the services may be kept up. It also provides a means whereby the central station operator may converse with any subscriber or he may place the subscribers into telephonic communication with each other.

The system it will also be noticed provides for the condition which would arise were one or more of the stations disabled for when that occurs that station may be cut out of the system and the station is, for the time being, placed in another circuit so as not to be rendered inoperative by the breaking down of a station between the same and the central station.

The construction of the various relays, switches and magnets may be of any ap-

proved mechanical or electro-mechanical type and I do not desire to be limited to the employment of any specific detailed construction in connection with my system as

5 the details of construction of the various relays and instrumentalities employed may be modified and adjusted to suit the requirements of the particular installations.

What I claim is:

- 10 1. In a mechanism of the class described, the
two sections of installation, each including a
main line circuit and a set of subscribers' stations, a central station from which each
of said main line circuits emanate, and a cen-
75
15 tral station apparatus at the central station
for each main line circuit; an interchanging station into which the terminal ends of the
two sections of installation are continued, an
interchanging apparatus at the said inter-
20 changing station, said interchanging apparatus including normal energizing batteries one for each section of installation,
said interchanging station including switching
and bridging devices operatively con-
25 trolled from the central station for oper-
atively connecting the terminal ends of one
section of installation to the other section
of installation, switching and bridging de-
30 vices at each subscriber's station, and in-
cluding means controlled from the central
station for locking out the subscribers' stations,
and suitable signaling apparatus at
the subscriber's station.
35 2. In a system of the class described, the
combination with two sections of installa-
tion, each including a central station appa-
ratus independent of the other, a main line
circuit, a series of subscribers' stations in the
40 main line circuit; combined with a common
interchanging terminal station into which
the terminal ends of the main line circuit
are carried, said two sections of installation
being operatively normally disconnected
45 from each other at the terminal station, and
means at the terminal station operatively
controlled from the central station over
either section of installation for operatively
connecting the main line circuit of one sec-
50 tion of installation into the main line cir-
cuit of the other set of installation; and
signaling mechanism at the subscriber's station
cooperative with the main line circuits.
55 3. In a system of the class described, the
combination with two sections of installa-
tion, each including a central station appa-
ratus independent of the other, a main line
circuit, a series of subscribers' stations in the
60 main line circuit; combined with a common
interchanging terminal station into which
the terminal ends of the main line circuit
are carried, said two sections of installation
being operatively normally disconnected
65 from each other at the terminal station, and
means at the terminal station operatively
controlled from the central station for
restoring the subscriber's station at the will
of the central station operator.
70 4. In a system of the class described, the
combination with two sections of installa-
tion, each including a central station appa-
ratus independent of the other, a main line
circuit, a series of subscribers' stations in
75 the main line circuit; combined with a com-
mon interchanging terminal station into
which the terminal ends of the main line
circuit are carried, said two sections of in-
80 stallation being operatively normally dis-
connected from each other at the terminal
station, and means at the terminal station
operatively controlled from the central sta-
85 tion over either section of installation for
operatively connecting the main line circuit
of one section of installation into the main
line circuit of the other set of installation;
90 and signaling mechanism at the subscriber's station
cooperative with the main circuits,
means at each subscriber's station and con-
trolled from the central for locking out and
restoring the subscriber's station at the will
95 of the central station operator, and means
at the subscribers' stations and controlled
from the central station for operatively dis-
connecting any station of a section.
100 5. In a system of the class described, the
combination with two sections of installa-
tion, each including a central station appa-
ratus independent of the other, a main line
circuit; combined with a common inter-
105 changing terminal station into which the
terminal ends of the main circuit are car-
ried, said two sections of installation being
operatively normally disconnected from each
other at the terminal station, and means at
110 the terminal station operatively controlled
from the central station over either section
of installation for operatively connecting the
main line circuit of one section of installa-
tion into the main line circuit of the other
115 set of installation; and signaling mechanism
at the subscriber's station cooperative with
the main line circuits, means at each sub-
scriber's station and controlled from the cen-
tral for locking out and restoring the sub-
scriber's station at the will of the central operator,
and means at the subscribers' stations and
controlled from the central station where-
120 by the subscriber's station at each side of the
125

disconnected station may be set for continuing the normal operation of all stations except the disconnected one.

6. In a system of the class described, a central station, a plurality of distinct line circuits emanating from the central station, an interchanging station into which the terminal ends of said circuits are run, an interchanging apparatus at said interchanging station, said interchanging apparatus including switching relays and bridging relays operable by current impulses over either of said main line circuits for operatively bridging the terminal ends of one of said main line circuits over onto the terminal ends of the other of said main line circuits and instrumentalities at the central station for effecting the operation of the interchanging station's apparatus.

20 7. In a system of the character described, a central station, a plurality of distinct main line circuit wires running out from the central station in separate sections of installation, an interchanging station into which the terminal ends of said main line wires of the respective sections of installation enter, mechanism at the interchanging station and controllable from the central for bridging over the line terminals of one section onto the line terminals of the other section whereby to provide a continuous circuit through the interchanging station, and a plurality of subscribers' stations on each section of installation, protecting apparatus at each subscriber's station for transmitting signal impulses to the central station, means at the central station for receiving said impulses, all being arranged substantially as shown and described.

40 8. In a system of the class described, a central station, two distinct sets of main line circuit wires emanating from the central station, a plurality of subscribers' stations on each section of installation, an interchanging station common to the terminal ends of both sections of installation, main line batteries located at the interchanging station for providing a normal current in the line wires of the respective sections of installation, separate sets of central station apparatus located at the central station, there being one set for each section of installation, auxiliary main line batteries at the subscribers' stations, mechanism at the interchanging station for bridging over the line terminal of the respective sections to form a through circuit at the interchanging station and disconnect the normal main line batteries at said interchanging station, instrumentalities at the central station for effecting the operation of the interchanging station apparatus, each subscriber's station apparatus including switch relays, bridging relays and a switching device for bringing said auxiliary main line batteries into circuit at times, said subscriber's station apparatus being controlled from the central station whereby a disabled subscriber's station may be disconnected from the section and the stations at each side of said disabled station may become line terminal stations, said subscriber's station apparatus and said central station apparatus also including a telephone set for effecting telephonic communication between the several stations.

batteries into circuit at times, said subscriber's station apparatus being controlled from the central station whereby a disabled subscriber's station may be disconnected from the section and the stations at each side of said disabled station may become line terminal stations.

9. In a system of the class described, a central station, two distinct sets of main line circuit wires emanating from the central station, a plurality subscribers' stations on each section of installation an interchanging station common to the terminal ends of both sections of installation, main line batteries located at the interchanging station for providing a normal current in the line wires of the respective sections of installation, separate sets of central station apparatus located at the central station there being one for each section of installation, auxiliary main line batteries at the subscribers' stations, mechanism at the interchanging station for bridging the line terminal of the respective sections to form a through circuit at the interchanging station and disconnect the normal main line batteries at said interchanging station, instrumentalities at the central station for effecting the operation of the interchanging station apparatus, each subscriber's station apparatus including switch relays, bridging relays and a switching device for bringing said auxiliary main line batteries into circuit at times, said subscriber's station apparatus being controlled from the central station whereby a disabled subscriber's station may be disconnected from the section and the stations at each side of said disabled station may become line terminal stations, said subscriber's station apparatus and said central station apparatus also including a telephone set for effecting telephonic communication between the several stations.

10. In a system of the class described, a central station, a plurality of distinct sets of installation including main line circuit wires emanating from the central station, interchanging stations into which the terminal ends of the main line wires of pairs of sections of installation terminate, a plurality of subscribers' stations in each section, each of said subscribers' stations including fire and burglar alarm apparatus, and an auxiliary apparatus for line testing and telephonic communication said interchanging station including switch relays, bridging relays and sources of electrical energy for normally maintaining a constant current in the main line wires of the respective sections of installation and for cutting out said constant current means and bridging over the line terminals of one section to another section, said interchanging station apparatus being controllable from the cen-

tral station, central station apparatus located at the central station for effecting the operation of the interchanging station apparatus and for effecting the operation of the subscriber's station apparatus.

- 5 11. In a system of the class described, a main line circuit and a plurality of subscribers' stations included in said main line circuit, signaling apparatus at the subscribers' stations, electro-mechanical means for automatically setting said signaling apparatus into action to transmit signaling impulses, signal receiving and controlling devices at the central station coöperative with 10 said subscriber's station signal apparatus, line testing and telephoning apparatus at the subscribers' stations and coöperative devices at the central station for effecting the 15 operation of said line testing and telephoning apparatus of the subscribers' stations.

12. In a system of the character described, a central station and a plurality of subscribers' stations, a main line circuit connecting all of said stations, alarm signal sending apparatus at the subscribers' stations, alarm signal receiving and indicating apparatus at the central station, means controlled at the central station for resetting the alarm signal apparatus of the subscribers' stations, line testing and telephone apparatus at the subscribers' stations connected in said main line circuit and including means controlled from the central station for setting the subscriber's station for line testing purposes, and means at the central station for applying the line tests and indicating the results thereof.

13. In a system of the character stated, a central station and a plurality of subscribers' stations, a main line circuit including all of said stations, a telephone set at the central station, said telephone set including a ground connection and a line connection, a telephone set at each subscriber's station and including a ground connection and a line connection, switching devices at each subscriber's station for bringing the telephone set of the subscriber's station into line connection, said means being controllable at the central station, instrumentalities at the subscribers' stations and controlled at the central station for disconnecting the subscriber's station from the central station after telephonic communication has been established between two of the subscribers' stations, and instrumentalities at the subscribers' stations and controlled at the central station for resetting the subscribers' stations apparatus.

14. In a system of the character stated, a

central station, a plurality of subscribers' stations, a main line circuit including all of said stations, a telephone set at each of said stations one terminal of which is grounded, and the other terminal is adapted to be connected to the main line circuit, switching devices at the subscribers' stations and operating means at the central station coöperative with said switching devices for setting the subscribers' stations 70 apparatus for telephonic communication, said subscribers' stations apparatus including devices whereby the subscribers' stations between any two stations set for telephonic communication, may be locked out of circuit, combined with alarm signal sending apparatus at the subscribers' stations, and signal receiving apparatus at the central station, said signal sending and receiving apparatus being connected with said main line 75 circuit, substantially as shown and described.

15. In a system of the character stated, a central station and a plurality of subscribers' stations, a main line circuit including 90 all of said stations, a telephone set at the central station, said telephone set including a ground connection and a line connection, a telephone set at each subscriber's station and including a ground connection and a 95 line connection, switching devices at each subscriber's station for bringing the telephone set of the subscriber's station into line connection, said means being controllable at the central station, instrumentalities at the 100 subscribers' stations and controlled at the central station for disconnecting the subscriber's station from the central station after telephonic communication has been established between two of the subscribers' 105 stations, and instrumentalities at the subscribers' stations and controlled at the central station for resetting the subscribers' stations apparatus.

16. In a system of the character stated, a central station, a plurality of subscribers' stations, a main line circuit including all of said stations, a telephone set at each of said stations one terminal of which is grounded, and the other terminal is adapted to be connected to the main line circuit, switching devices at the subscribers' stations and operating means at the central station coöperative with said switching devices for setting the subscribers' stations apparatus for telephonic communication, said subscribers' stations apparatus including devices whereby the subscribers' stations between any two stations set for telephonic communication, may be locked out of circuit, automatic 110 alarm signal sending apparatus at the subscribers' stations and connected with said main line circuit, and alarm signal receiving apparatus at the central station also connected with said main line circuit, and 115 120 125 130

means controlled at the central station for resetting the subscribers' stations apparatus.

17. In a system of the character stated, a central station, a plurality of subscribers' stations and a main line circuit connecting all of said stations, a telephone set at each station, one terminal of which is grounded and the other terminal is adapted to be connected to the main line circuit, two sets of apparatus at the subscribers' stations, the first of said sets of apparatus including alarm signal sending instrumentalities for transmitting signaling impulses to the central station over the main line circuit, and including means for operatively disconnecting the second set of apparatus and the stations beyond the station nearest the central station which is sending in a signal, from the main line circuit, the second set of apparatus including switching devices operatively controlled at the central station for setting the subscriber's station apparatus for line testing and telephonic purposes; means at the central station for receiving and indicating the telegraphic impulses, means at the central station for indicating the line tests, and means controlled at the central station for resetting both sets of subscriber's station apparatus.
18. In a system of the class described, a central station, a plurality of sets of installations, each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station, operatively controlled from the central station and responding to current impulses entering the interchanging station over either section, for operatively disconnecting the normal main line sources of energy and bridging over the terminal ends of the main line circuits of the two sections to form a through connection between the same at the interchanging station.
19. In a system of the class described, a central station, a plurality of sets of installations each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station over either section, for operatively disconnecting the normal main line sources of energy and bridging over the terminal ends of the main line circuits of the two sections to form a through connection between the same at the interchanging station, and mechanism at the interchanging station and controlled by current impulses from the central station for resetting the interchanging station apparatus to its normal condition, said central station apparatus including means cooperative with said resetting means to effect the operation of the same.
20. In a system of the class described, a central station, a plurality of sets of installations, each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station, operatively controlled from the central station and responding to current impulses entering the interchanging station over either section, for operatively disconnecting the normal main line sources of energy and bridging over the terminal ends of the main line circuits of the two sections to form a through connection between the same at the interchanging station, each of the subscribers' stations including alarm signal sending apparatus connected in the main line circuit for sending telegraphic impulses to the central station, the central station including apparatus for receiving and indicating the impulses so transmitted, and means controlled at the central station for resetting the subscriber's station signaling apparatus.
21. In a system of the class described, a central station, a plurality of sets of installations each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station over either section, for operatively disconnecting the normal main line sources of energy and bridging over the terminal ends of the main line circuits of the two sections to form a through connection between the same at the interchanging station, and mechanism at the interchanging station and controlled by current impulses from the central station for resetting the interchanging station apparatus to its normal condition, said central station apparatus including means cooperative with said resetting means to effect the operation of the same.

the interchanging station, operatively controlled from the central station and responding to current impulses entering the interchanging station over either section, for operatively disconnecting the normal main line sources of energy and bridging over the terminal ends of the main line circuits of the two sections to form a through connection between the same at the interchanging station, mechanism at the interchanging station and controlled by current impulses from the central station for resetting the interchanging station to its normal condition, said central station apparatus including means coöperative with said resetting means to effect the operation of the same, each of the subscribers' stations including alarm signal sending apparatus connected in the main line circuit for sending telegraphic signals to the central station, the central station including apparatus for receiving and indicating the signals so transmitted and means controlled at the central station for resetting the subscriber's station signal sending apparatus.

22. In a system of the class described, a central station, a plurality of sets of installations each including a plurality of subscribers' stations and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, each of the subscribers' stations including alarm signal sending apparatus connected in the main line circuit for sending telegraphic impulses to the central station, the central station including apparatus for receiving and indicating the impulses so transmitted, means controlled at the central station for resetting the subscriber's station signal sending apparatus, the subscriber's station signal sending apparatus including main line circuit opening devices for operatively disconnecting the stations beyond the one whose signal is being received at the central station during the time such signal is being received at the central station and until the particular subscriber's station apparatus has been reset.

23. In a system of the class described, a central station, a plurality of sets of installations each including a plurality of subscribers' stations and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, mechanism at the interchanging station and controlled by current impulses from the central station for resetting the interchanging station to its normal condition, said central station apparatus including means coöperative with said resetting means to effect the operation of the same, each of the subscribers' stations including alarm signal sending apparatus connected in the main line circuit for sending telegraphic impulses to the central station, the central station including apparatus for receiving and indicating the signals so transmitted, means controlled at the central station for resetting the subscriber's station signal sending apparatus, the subscriber's station signal sending apparatus including main line circuit opening devices for operatively disconnecting the stations beyond the one whose signal is being received at the central station during the time such signal is being received at the central station and until the particular subscriber's station apparatus has been reset.

24. In a system of the class described, a central station, a plurality of sets of installations each including a plurality of subscribers' stations and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, mechanism at the interchanging station and controlled by current impulses from the central station for resetting the interchanging station to its normal condition, the subscriber's station signal sending apparatus including main line circuit opening devices for operatively disconnecting the stations beyond the one whose signal is being received at the central station during the time such signal is being received at the central station and until the particular subscriber's station apparatus has been reset.

- eratively disconnecting the normal main line sources of energy and bridging over the terminal ends of the main line circuits of the two sections to form a through connection 5 between the same at the interchanging station, said subscriber's station apparatus and said central station apparatus each including a telephone set, one terminal of which is grounded and the other terminal is adapted to be connected to the main line circuit, each of said subscriber's station apparatus including switching devices operative by current impulses entering the subscriber's station from the central station for selectively connecting a subscriber's station for telephonic communication, and means at each subscriber's station for locking out the subscribers' stations not set for telephonic communication.

20 25. In a system of the class described, a central station, a plurality of sets of installations each including a plurality of subscribers' stations and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, said subscriber's station apparatus and said central station apparatus each including a telephone set, one terminal of which is grounded and the other terminal is adapted to be connected to the main line circuit, each of said subscriber's station apparatus including switching devices operative by current impulses entering the subscriber's station from the central station for selectively connecting a subscriber's station for telephonic communication, and means at each subscriber's station for locking out the subscribers' stations not set for telephonic communication, and means controlled at the central station for resetting the subscribers' stations apparatus.

25 30 35 40 45 50 55 60 65 70 75 80 85 90 95 100 105 110 115 120 125 130

27. In a system of the class described, a central station, a plurality of sets of installations each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, means at the interchanging station and controlled by current impulses from the central station for resetting the interchanging station to its normal condition, said central station apparatus including means coöperative with said resetting means to effect the operation of the same, said subscriber's station apparatus and said central station apparatus each including a telephone set, one terminal of which is grounded and the other terminal is adapted to be connected to the main line circuit, each of said subscriber's station apparatus including switching devices operative by current impulses entering the subscriber's station from the central station for selectively connecting a subscriber's station for telephonic communication, and means at each subscriber's station for locking out the subscribers' stations not set for telephonic communication.

26. In a system of the class described, a central station, a plurality of sets of installations each including a plurality of subscribers' stations and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, means at the interchanging station and controlled by current impulses from the central station for resetting the interchanging station to its normal condition, said central station apparatus including means coöperative with

- said resetting means to effect the operation of the same, said subscriber's station apparatus and said central station apparatus each including a telephone set, one terminal of which is grounded and the other terminal is adapted to be connected to the main line circuit, each of the subscriber's station apparatus including switching devices operative by current impulses entering the subscriber's station from the central station for selectively connecting a subscriber's station for telephonic communication, means at each subscriber's station for locking out the subscribers' stations not set for telephonic communication, and means controlled at central station for resetting the subscriber's station apparatus.
28. In a system of the class described, a central station, a plurality of sets of installations, each including a plurality of subscribers' stations, and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, mechanism at the interchanging station and controlled by current impulses from the central station for resetting the interchanging station to its normal condition, said central station apparatus including means coöperative with said resetting means to effect the operation of the same, each of the subscribers' stations including alarm signal sending apparatus connected in the main line circuit for sending telegraphic impulses to the central station, the central station including apparatus for receiving and indicating the signals so transmitted, means controlled at the central station for resetting the subscriber's station signal sending apparatus, each subscriber's station apparatus also including an auxiliary apparatus, said auxiliary apparatus including a telephone set, one terminal of which is grounded and the other terminal is adapted to be connected with the main line circuit, said auxiliary apparatus including switching devices operatively controlled at the central station for selectively connecting the telephone set of a subscriber's station with that of another subscriber's station and locking out the intermediate subscribers' stations, and means controllable at the central station for resetting said auxiliary apparatus.
30. In a system of the class described, a central station, a plurality of sets of installations each including a plurality of subscribers' stations and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instru-

- mentalities at the interchanging station operatively controlled from the central station and responding to current impulses entering the interchanging station over either section 5 for operatively disconnecting the normal main line sources of energy and bridging over the terminal ends of the main line circuits of the two sections to form a through connection between the same at the interchanging station, each of the subscribers' stations including alarm signal sending apparatus connected in the main line circuit for sending signaling impulses to the central station, the central station including apparatus 10 for receiving and indicating the signals so transmitted, means controlled at the central station to resetting the subscriber's station signal setting apparatus, the subscriber's station signal setting apparatus including main line circuit opening devices for operatively disconnecting the stations beyond the one whose signal is being received at the central station during the time such signal is being received at the central 15 station and until the particular subscriber's station apparatus has been reset, each subscriber's station apparatus also including an auxiliary apparatus, said auxiliary apparatus including a telephone set, one terminal of which is grounded, and the other terminal is adapted to be connected with the main line circuit, said auxiliary apparatus including switching devices operatively controlled at the central station for selectively connecting the telephone set of a subscriber's station with that of another subscriber's station and locking out the intermediate subscribers' stations, and means controllable at the central station for resetting said auxiliary apparatus. 20
31. In a system of the class described, a central station, a plurality of sets of installations each including a plurality of subscribers' stations, and a main line circuit connecting said subscribers' stations with the central station, a distinct set of apparatus at the central station for each section of installation, and interchanging station into which the terminal ends of the main 25 line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, each of the subscribers' stations including alarm signal sending apparatus connected in the main line circuit for sending telegraphic impulses to the central station, the central station including apparatus for receiving and indicating the 30
- rent impulses from the central station for resetting the interchanging station to its normal condition, said central station apparatus including means coöperative with said resetting means to effect the operation of the same, each of the subscribers' stations including alarm signal sending apparatus connected in the main line circuit for sending telegraphic impulses to the central station, the central station including apparatus for receiving and indicating the signals so transmitted means controlled at the central station for resetting the subscriber's station signal sending apparatus, the subscriber's station signal sending apparatus including main line circuit opening devices for operatively disconnecting the stations beyond the one whose signal is being received at the central station during the time such signal is being received at the central station and until the particular subscriber's station apparatus has been reset, each subscriber's station apparatus including an auxiliary apparatus, said auxiliary apparatus including telephone set, one terminal of which is grounded, and the other terminal is adapted to be connected with the main line circuit, said auxiliary apparatus including switching devices operatively controlled at the central station for selectively connecting the telephone set of a subscriber's station with that of another subscriber's station and locking out of the intermediate subscribers' stations, and means controllable at the central station for resetting said auxiliary apparatus. 35
32. In a system of the class described, a central station, a plurality of sets of installations, each including a plurality of subscribers' stations, and a main line circuit connecting said subscribers' stations with the central station, a distinct set of apparatus at the central station for each section of installation, an interchanging station into which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and bridging over the terminal ends of the main line circuits of the two sections to form a through connection between the same at the interchanging station, each of the subscribers' stations including alarm signal sending apparatus connected in the main line circuit for sending telegraphic impulses to the central station, the central station including apparatus for receiving and indicating the 40

signals so transmitted, means controlled at the central station for resetting the subscriber's station signaling apparatus, each subscriber's station apparatus also including 5 an auxiliary apparatus, said auxiliary apparatus including a telephone set, one terminal of which is grounded and the other terminal is adapted to be connected with the main line circuit, said auxiliary apparatus including 10 switching devices operatively controlled at the central station for selectively connecting the telephone set of a subscriber's station with that of another subscriber's station and locking out the intermediate subscribers' stations, means controllable at the central station for resetting said auxiliary apparatus, 15 said auxiliary apparatus also including auxiliary main line terminal batteries, a switching device for bringing said terminal batteries into operative relation to the main line, and another switching device for changing the line terminal connections of the subscribers' stations apparatus accordingly as said subscriber's station is connected 20 to one set of installation or the other, said switching devices being operatively controlled at the central station.

33. In a system of the class described, a central station, a plurality of sets of installations each including a plurality of subscribers' stations, and a main line circuit connecting said subscribers' stations with the central station, a distinct set of apparatus at the central station for each section of installation, an interchanging station in which the terminal ends of the main line circuits of two sections of installation terminate, normal main line sources of energy at the interchanging station for maintaining closed circuit currents in the main line circuits of the respective sections, instrumentalities at the interchanging station operatively controlled from the central station and responding to current impulses entering 40 the interchanging station over either section for operatively disconnecting the normal main line sources of energy and bridging over the terminal ends of the main line circuits of the two sections to form a through 45 connection between the same at the interchanging station, mechanism at the interchanging station and controlled by current impulses from the central station for resetting the interchanging station apparatus to its normal condition, said central station apparatus including means coöperative with 50 said resetting means to effect the operation of the same, each of the subscribers' stations including alarm signal sending apparatus connected in the main line circuit for sending telegraphic impulses to the central station, the central station including apparatus for receiving and indicating the signals so transmitted, means at the central station for

resetting the subscriber's station signal setting apparatus, each subscriber's station apparatus also including an auxiliary apparatus, said auxiliary apparatus including a telephone set, one terminal of which is grounded and the other terminal is adapted 70 to be connected with the main line circuit, said auxiliary apparatus including switching devices operatively controlled at the central station for selectively connecting the telephone set of a subscriber's station with 75 that of another subscriber's station and locking out the intermediate subscribers' stations, means controllable at the central station for resetting said auxiliary apparatus, said auxiliary apparatus also including auxiliary main line terminal batteries, a switching device for bringing said terminal batteries into operative relation to the main line and another switching device for changing the line terminal connections of the subscribers' stations apparatus accordingly as 80 said subscriber's station is connected to one set of installation or the other, said switching devices being operatively controlled at the central station. 90

34. In a system of the class described, a central station, a plurality of sets of installations each including a plurality of subscribers' stations and a main line circuit connecting said subscribers' stations with the central station, a distinct set of apparatus at the central station for each section of installation, an interchanging station into which the terminal ends of the main line circuits of two sections of installation 100 terminate, normal main line sources of energy at the interchanging station for maintaining closed circuit currents in the main line circuits of the respective sections, instrumentalities at the interchanging station operatively controlled from the central station and responding to current impulses entering the interchanging station over either section for operatively disconnecting the normal main line sources of energy and 105 bridging over the terminal ends of the main line circuits of the two sections to form a through connection between the same at the interchanging station, each of the subscribers' stations including alarm signal 110 sending apparatus connected in the main line circuit for sending telegraphic impulses to the central station, the central station including apparatus for receiving and indicating the signals so transmitted, means controlled at the central station for resetting the subscriber's station signal sending apparatus including main line circuit opening devices for operatively disconnecting the stations beyond the one whose signal is being received at the central station during the time such signal is being received at the central station and until the particular sub- 120 125

scriber's station apparatus has been reset, each subscriber's station apparatus also including an auxiliary apparatus, said auxiliary apparatus including a telephone set, 5 one terminal of which is grounded, and the other terminal is adapted to be connected with the main line circuit, said auxiliary apparatus including switching devices operatively controlled at the central station 10 for selectively connecting the telephone set of a subscriber's station with that of another subscriber's station and locking out the intermediate subscribers' stations, means controllable at the central station for resetting said auxiliary apparatus, said auxiliary apparatus also including auxiliary main line terminal batteries, a switching device for bringing said terminal batteries into operative relation to the main line, and another 15 switching device for changing the line terminal connections of the subscribers' stations apparatus accordingly as said subscriber's station is connected to one set of installation or the other, said switching devices being operatively controlled at the central station. 20

35. In a system of the class described, a central station, a plurality of sets of installations each including a plurality of subscribers' stations, and a main line circuit connecting said subscribers' stations with the central station, a distinct set of apparatus at the central station for each section of installation, an interchanging station in 30 which the terminal ends of the main line circuits of two sections of installation terminate, normal main line sources of energy at the interchanging station for maintaining closed circuit currents in the main line 35 circuits of the respective sections, instrumentalities at the interchanging station operatively controlled from the central station and responding to current impulses entering the interchanging station over either 40 circuits of the respective sections, a section for operatively disconnecting the normal main line sources of energy and bridging over the terminal ends of the main line circuits of the two sections to form a through connection between the same at 45 the interchanging station, mechanism at the interchanging station and controlled by current impulses from the central station for resetting the interchanging station to its normal condition, said central station apparatus including means co-operating with 50 said resetting means to effect the operation of the same, each of the subscribers' stations including alarm signal sending apparatus connected in the main line circuit for sending 55 telegraphic impulses to the central station, the central station including apparatus for receiving and indicating the signals so transmitted, means at the central station for resetting the subscriber's station signal 60

sending apparatus, the subscriber's station 65 signal sending apparatus including main line circuit opening devices for operatively disconnecting the stations beyond the one whose signal is being received at the central station during the time such signal is being 70 received at the central station and until the particular subscriber's station apparatus has been reset, each subscriber's station apparatus including an auxiliary apparatus, said auxiliary apparatus including a telephone set, one terminal of which is grounded, and the other terminal is adapted to be connected with the main line circuit, said auxiliary apparatus including switching devices 75 operatively controlled at the central station for selectively connecting the telephone set of a subscriber's station with that of another subscriber's station and locking out the intermediate subscribers' stations, means controllable at the central station for 80 resetting said auxiliary apparatus, said auxiliary apparatus also including auxiliary main line terminal batteries, a switching device for bringing said terminal batteries into operative relation to the main line and 85 another switching device for changing the line terminal connections of the subscribers' stations apparatus accordingly as said subscriber's station is connected to one set of installation or the other, said switching devices being operatively controlled at the central station. 90

36. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling 100 device into action, there being at least two automatic switches at each subscriber's station, burglar alarm circuit closers co-operating with one of said switches, and fire alarm circuit closers co-operating with the other of 105 said switches, main line sources of energy at the subscribers' stations, co-operative connections between said switches and said sources of energy for bringing said sources of energy into operative relation with said signaling devices to send out the signal impulses into the main line circuit upon closing the burglar or fire alarm circuit closers 110 at a station, signal receiving apparatus at the central station, an auxiliary apparatus 115 at each subscriber's station, said auxiliary apparatus being connected in said main line circuit and including a telephone set, one terminal of which is grounded and the other terminal adapted to be connected operatively with the main line circuit, said auxiliary apparatus also including switching devices 120 for operatively connecting said tele-

phone set with the main line circuit, said central station apparatus including instrumentalities co-operative with said auxiliary apparatus switching devices for setting and resetting the same.

37. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscribers' stations.

38. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the

central station, means at each subscriber's station for cutting out of the circuit the succeeding stations to the one whose signal is being transmitted to the central station, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same. 70 75 80

39. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, means at each subscriber's station for cutting out of the circuit the succeeding stations to the one whose signal is being transmitted to the central station, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station. 120

40. In a system of the class described, a central station and a set of subscribers' stations, a main line circuit connecting the respective stations, a signaling device at each subscriber's station for sending out telegraphic signals into the main line circuit, 130

- automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, means at the central station coöperating with the switching devices at the subscriber's station for resetting the subscriber's station apparatus, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same. 41. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, means at each subscriber's station for cutting out of the circuit the succeeding stations to the one whose signal is being transmitted to the central station, means at the central station coöperating with the switching devices at the subscriber's station for resetting the subscriber's station apparatus, an auxiliary apparatus at each subscriber's station, said auxiliary apparatus connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same. 42. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, and signal receiving apparatus at the central station, means at each subscriber's station for cutting out of the circuit the succeeding stations to the one whose signal is being transmitted to the central station, means at the central station coöperating with the switching devices at the subscriber's station for resetting the subscriber's station apparatus, an auxiliary apparatus at each subscriber's station, said auxiliary apparatus connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same. 43. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, means at each subscriber's station for cutting out of the circuit the succeeding stations to the one whose signal is being transmitted to the central station, means at the central station coöperating with the switching devices at the subscriber's station for resetting the subscriber's station apparatus, an auxiliary apparatus at each subscriber's station, said auxiliary apparatus connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.

- device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, signal receiving apparatus at the central station, means at each subscriber's station for cutting out of the circuit the succeeding stations to the one whose signal is being transmitted to the central station, means at the central station coöperating with the switching devices at the subscriber's station for resetting the subscriber's station apparatus, an auxiliary apparatus at each subscriber's station, said auxiliary apparatus being connected in said main line circuit and including a telephone set one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.
44. In a system of the class described, a central station and a set of subscribers' stations, a main line circuit connecting all of said stations, means at the end of the system for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit with the central station and cutting out the succeeding subscriber's station from connection with the central station upon closing one of said circuit closers, an auxiliary apparatus at the subscriber's station, said auxiliary apparatus being connected in said main line circuit and including a telephone set, one terminal of which is grounded, and the other terminal adapted to be connected operatively with the main line circuit, said auxiliary apparatus also including switching devices for

operatively connecting said telephone set with the main line circuit, said central station apparatus including instrumentalities coöperative with said auxiliary apparatus switching devices for setting and resetting the same. 70

45. In a system of the class described, a central station and a set of subscribers' stations, a main line circuit connecting all of said stations, means at the end of the system for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, means at the subscriber's station coöperative with said signaling apparatus, and including normally open circuit closers, for bringing said signaling apparatus into circuit with the central station and cutting out the succeeding subscribers' stations from connection with the central station upon closing one of the said circuit closers, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station. 100

46. In a system of the class described, a central station and a set of subscribers' stations, a main line circuit connecting all of said stations, means for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit with the central station and cutting out the succeeding subscribers' stations from connection with the central station upon closing one of said circuit closers, said last named means including an automatic switching device, said automatic switching device including operating mag- 130

- nets having two distinct windings, a local battery circuit connected with one of said windings and with said circuit closer, a main line circuit branch connecting the other of 5 said windings with the main line, said circuit branch including normally open contacts at said switching device that are closable by said switching device when said switching device is operated by said local 10 circuit, an auxiliary apparatus at each subscriber's station, said auxiliary apparatus being connected in said main line circuit and including a telephone set, one terminal of which is grounded, and the other terminal 15 adapted to be connected operatively with the main line circuit, said auxiliary apparatus also including switching devices for operatively connecting said telephone set with the main line circuit, said central station apparatus 20 including instrumentalities coöperative with said auxiliary apparatus switching devices for setting and resetting the same.
47. In a system of the class described, a 25 central station and a set of subscribers' stations, a main line circuit connecting all of said stations, means for maintaining a normal closed circuit current in said main line circuit, a signaling relay at the central station 30 in said main line circuit, means at the central station coöperative with said relay for normally balancing said normal closed circuit current, a signaling apparatus at each subscriber's station normally disconnected 35 from said main line circuit, and means at the subscriber's station coöperative with said signaling apparatus, and including normally open circuit closers, for bringing said signaling apparatus into circuit 40 with the central station and cutting out the succeeding subscribers' stations from connection with the central station upon closing one of said circuit closers, said last named means including an automatic switching device, 45 said automatic switching device including operating magnets having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit, means at the central station for sending a reverse current through the main line circuit, and said main line circuit winding of said switching device magnet for resetting said switching device and thereby restoring the subscriber's station apparatus to its initial position after said local circuit has been opened, an auxiliary apparatus 50 at each subscriber's station, said auxiliary apparatus being connected in said main line circuit and including a telephone set, one terminal of which is grounded, and the other terminal adapted to be connected 55 operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
48. In a system of the class described, a central station and a set of subscribers' stations, a main line circuit connecting all of said stations, means for maintaining a normal closed circuit current in said main line circuit, a signaling relay at the central station 60 in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit 65 with the central station and cutting out the succeeding subscriber's station from connection with the central station upon closing one of said circuit closers, said last named means including an automatic switching device 70 including an operating magnet having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit, means at the central station for locking out the subscriber's 75 station.
49. In a system of the class described, a central station and a set of subscribers' stations, a main line circuit connecting all of said stations, means for maintaining a normal closed circuit current in said main line circuit, a signaling relay at the central station 80 in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit 85 with the central station and cutting out the succeeding subscriber's station from connection with the central station upon closing one of said circuit closers, said last named means including an automatic switching device 90 including an operating magnet having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit, means at the central station for sending a reverse current through the main line circuit, and said main line circuit winding of said switching device magnet for resetting said switching device and thereby restoring the subscriber's station apparatus to its initial position after said local circuit has been opened, an auxiliary apparatus 95 at each subscriber's station, said auxiliary apparatus being connected in said main line circuit and including a telephone set, one terminal of which is grounded, and the other terminal adapted to be connected 100 operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
50. In a system of the class described, a central station and a set of subscribers' stations, a main line circuit connecting all of said stations, means for maintaining a normal closed circuit current in said main line circuit, a signaling relay at the central station 105 in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit 110 with the central station and cutting out the succeeding subscriber's station from connection with the central station upon closing one of said circuit closers, said last named means including an automatic switching device 115 including an operating magnet having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit, means at the central station for locking out the subscriber's 120 station.
51. In a system of the class described, a central station and a set of subscribers' stations, a main line circuit connecting all of said stations, means for maintaining a normal closed circuit current in said main line circuit, a signaling relay at the central station 125 in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit 130 with the central station and cutting out the succeeding subscriber's station from connection with the central station upon closing one of said circuit closers, said last named means including an automatic switching device

central station coöperative with said relay for normally balancing said normal closed circuit current, a signaling apparatus at each subscriber's station normally disconnected 5 from said main line circuit, and means at the subscriber's station coöperative with said signaling apparatus, and including normally open circuit closers, for bringing said signaling apparatus into circuit with the central station upon closing one of said circuit closers, said last named means including an automatic switching device, said automatic switching device including operating magnets having two distinct 70 windings, a local battery circuit connected with one of said windings and with said circuit closer, a main line circuit branch connecting the other of said windings with the main line, said circuit branch including 75 normally open contacts at said switching device that are closable by said switching device when said switching device is operated by said local circuit, said subscriber's station signaling apparatus including two 80 distinct sets of signaling contacts one for the main line circuit and the other for a local circuit, and a local battery circuit including a signal and said other set of contacts whereby signals will be alternately im- 85 pulsed to the central station and to the local signal of the subscriber's station, an auxiliary apparatus at the subscriber's station, said auxiliary apparatus being connected in said main line circuit and including a tele- 90 phone set, one terminal of which is grounded, and the other terminal adapted to be connected operatively with the main line circuit, said auxiliary apparatus also including switching devices for operatively 95 connecting said main line circuit, said central station apparatus including instrumentalities coöperative with said auxiliary apparatus switching devices for setting and resetting the same. 100

50. In a system of the class described, a central station and a set of subscribers' stations, a main line circuit connecting all of said stations, means for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, means at the subscriber's station coöperative with said signaling apparatus, and including normally open circuit closers, for bringing said signaling apparatus into circuit with the central station and cutting out the succeeding subscriber's stations from connection with the central station upon closing one of said circuit closers, said last named means including an automatic switching device, said automatic switching device including operating magnets having two distinct windings, a local battery circuit connected with one of said windings and with said circuit closer, and a main line circuit branch connecting the other of said windings with the main line, said circuit branch including normally open contacts at said switching device that are clos- 125 130

- able by said switching device when said switching device is operated by said local circuit, said subscriber's station signaling apparatus including two distinct sets of 5 signaling contacts one for the main line circuit and another for a local circuit, a local battery circuit including a signal and said other set of contacts whereby signals will be alternately impelled to the central station and to the local signal of the subscriber's station, an auxiliary apparatus at each subscriber's station, said auxiliary apparatus being connected in said main line circuit and including a telephone set, one terminal of 10 which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices 15 for setting and resetting the same. 53. In a system of the class described, a central station and a set of subscribers' stations, a main line circuit connecting all of 20 said stations, means for maintaining a normal closed circuit current in said main line circuit, a signaling relay at the central station in said main line circuit, means at the central station coöperative with said relay for normally balancing said normal closed 25 circuit current, a signaling apparatus at each subscriber's station normally disconnected from said main line circuit, and means at the subscriber's station coöperative with said signaling apparatus, and including normally 30 open circuit closers, for bringing said signaling apparatus into circuit with the central station and cutting out the succeeding subscribers' stations from connection with the central station upon closing one of said circuit closers, said last named means including an automatic switching device, said automatic switching device including operating magnets 35 having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit, and means at the central station for sending a reverse current through the main line circuit, and said main line circuit winding of said switching device magnet for resetting said switching device and thereby restoring the subscriber's station apparatus to their initial position after said local circuit has been opened, said subscriber's station signaling apparatus including two distinct sets of signaling contacts one for the main line circuit and another for a local circuit, and a local battery circuit including a signal and said other set of contacts where- 40 45 50 55 60 65 70 75 80 85 90 95 100 105 110 115 120 125 130

by signals will be alternately impelled to the central station and to the local signal of the subscriber's station, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus 70 switching devices for setting and resetting the same.

5 54. In a system of the character described, a central station and a set of subscribers' stations, a main line circuit connecting all of said stations, means for maintaining a normal current in the main line circuit whereby the same is normally a closed circuit, a signaling relay in the central station including a winding connected in said main line circuit, and a local balancing winding, a local balancing circuit at the 80 central station connected with said balancing winding to hold said relay normally inoperative, two distinct sets of signals controlled by said relay, a signaling device at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and coöperative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, means for opening the main line circuit to stations beyond the nearest station to the central station which is sending in a signal, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus 100 also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.

10 55. In a system of the character described, a central station and a set of subscribers' stations, a main line circuit connecting all of said stations, means for maintaining a normal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and coöperative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, means for opening the main line circuit to stations beyond the nearest station to the central station which is sending in a signal, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.

15 56. In a system of the character described, a central station and a set of subscribers' stations, a main line circuit connecting all of said stations, means for maintaining a normal

ratus also including switching devices for operatively connecting said telephone set with the main line circuit, said central station apparatus including instrumentalities coöperative with said auxiliary apparatus 70 switching devices for setting and resetting the same.

55. In a system of the character described, a central station and a set of subscribers' stations, a main line circuit connecting all of said stations, means for maintaining a normal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and coöperative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, means for opening the main line circuit to stations beyond the nearest station to the central station which is sending in a signal, an auxiliary apparatus at each subscriber's station, said auxiliary apparatus being connected in said main line circuit and including a telephone set, one terminal of which is grounded and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.

90 56. In a system of the character described, a central station and a set of subscribers' stations, a main line circuit connecting all of said stations, means for maintaining a normal

- mal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, said signaling device including two distinct signaling disks, two automatic switching devices at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and coöperative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, means for opening the main line circuit to stations beyond the nearest station to the central station which is sending in a signal, means operable at the central station for restoring said switching device to their initial position to thereby reset the subscriber's station apparatus, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including switching devices for operatively connecting said telephone set with the main line circuit, said central station apparatus including instrumentalities coöperative with said auxiliary apparatus switching devices for setting and resetting the same.
57. In a system of the character described, a central station and a set of subscribers' stations, a main line circuit connecting all of said stations, means for maintaining a normal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, said signaling device including two distinct signaling disks, two automatic switching devices at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and coöperative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, means for opening the main line circuit to stations beyond the nearest station to the central station which is sending in a signal, means operable at the central station for restoring said switching device to their initial position to thereby reset the subscriber's station apparatus, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.
58. In a system of the class described, a central station and a plurality of subscribers' stations, a main line circuit connecting the respective stations and including a source of energy for maintaining a normal current in said main line circuit, a signal receiving apparatus in said central station including operating magnets having a winding connected in said main line circuit, and also including a local balance winding, a local balancing winding circuit at the central station including said balancing; normally inoperative means at each subscriber's station for sending telegraphic signal impulses into the main line circuit to the central station, means at each subscriber's station for setting said signaling means into operation at times, means at each subscriber's station coöperative with said setting means for cutting the main line circuit to subscriber's station beyond, the signaling

means of each subscriber's station when set being adapted to operate for an indefinite time regardless of whether or not the main line circuit of a particular station is open to the central station, means at the central station for resetting the apparatus at the particular subscriber's station which is in operative connection with the central station and thereby bring the next succeeding station into connection with the central station whereby its signal may be received at the central station, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.

59. In a system of the class described, a central station and a plurality of subscribers' stations, a main line circuit connecting the respective stations and including a source of energy for maintaining a normal current in said main line circuit, a signal receiving apparatus at the central station including operating magnets having a winding connected in said main line circuit, and also including a local balancing winding, a local balancing circuit at the central station including said balancing winding; normally inoperative means at each subscriber's station for sending telegraphic signal impulses into the main line circuit to the central station, means at each subscriber's station for setting said signaling means into operation at times, means at each subscriber's station coöperative with said setting means for cutting the main line circuit to subscriber's station beyond, the signaling means of each subscriber's station when set being adapted to operate for an indefinite time regardless of whether or not the main line circuit of a particular station is open to the central station, means at the central station for resetting the apparatus at the particular subscriber's station which is in operative connection with the central station and thereby bring the next succeeding station into connection with the central station whereby its signal may be received at the central station, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switch-

ing devices for operatively connecting said telephone set with the main line circuit, said central-station apparatus including instrumentalities coöperative with said auxiliary apparatus switching devices for setting and resetting the same, said auxiliary apparatus also including means controlled at the central station for locking out the subscriber's station.

60. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the signaling apparatus into connection with the main line circuit whereby the signals may be impelled to the central station, means controllable at the central station and coöperating with said switches for resetting the subscriber's apparatus, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.

61. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the signaling apparatus into connection with the main line circuit whereby the signals may be impelled to the central station, means controllable at the central station and coöperating with said switches for resetting the subscriber's ap-

- paratus, an auxiliary apparatus at each subscriber's station, said auxiliary apparatus being connected in said main line circuit and including a telephone set, one terminal 5 of which is grounded, and the other terminal adapted to be connected operatively with the main line circuit, said auxiliary apparatus also including switching devices for operatively connecting said telephone set 10 with the main line circuit, said central station apparatus including instrumentalities coöperative with said auxiliary apparatus switching devices for setting and resetting the same, said auxiliary apparatus also including means controlled at the central station for locking out the subscriber's station. 15
62. In a system of the class described, a central station and a plurality of subscribers' stations, a main line circuit connecting 20 the respective stations and including a constant current source of energy, a signal receiving apparatus at the central station connected in the main line circuit and normally balanced so as to be non-operative by the 25 normal main line current, a signaling device at each subscriber's station, said signaling device including a plurality of distinct signal sending sections, separate switching devices coöperative with each section, 30 separate means at the subscriber's station for operating the respective switches to set the respective section of the signaling apparatus into connection with the main line circuit whereby the signals may be impelled to the central station, means controllable at 35 the central station and coöperating with said switches for resetting the subscriber's apparatus, local signals at the subscriber's 40 signaling apparatus whereby when the signaling apparatus of a station is set into operation a local signal will also be actuated, an auxiliary apparatus at each subscriber's station, said auxiliary apparatus also including means controlled at the central station for locking out the subscriber's station. 45
64. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate 50 switching devices coöperative with each section, separate means at the subscriber's station for operating the respective switches to set the respective section of the signaling apparatus into connection with the main line circuit whereby the signals may be impelled to the central station, and means controllable at the central station and coöperative with said switches for resetting the subscriber's apparatus, means coöperative with the respective switching devices for breaking the main line circuit to stations beyond the particular station whose signaling apparatus has been set into action, whereby only the station in operation 55 nearest the central station will have its signals transmitted to the central station, an auxiliary apparatus at each subscriber's station, said auxiliary apparatus being connected in said main line circuit and including a telephone set, one terminal of which is grounded, and the other terminal operatively connected with the main line circuit, said auxiliary apparatus also including switching devices for operatively connecting said telephone set with the main line circuit, said central station apparatus including instrumentalities coöperative with said auxiliary apparatus switching devices for setting and resetting the same. 60
63. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a 65

- is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
65. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the signaling apparatus into connection with the main line circuit whereby the signals may be impelled to the central station, means controllable at the central station and coöperating with said switches for resetting the subscriber's apparatus, means coöperative with the respective switching devices for breaking the main line circuit to stations beyond the particular station whose signaling apparatus has been set into action, whereby only the station in operation nearest the central station will have its signals transmitted to the central station, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same, said auxiliary apparatus also including means controlled at the central station for locking out the subscriber's station.
66. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each

subscriber's station for bringing said signaling device and its coöperative source of energy into connection with the main line circuit at times, whereby the station's signal may be impelled into the main line to the central station, means at the subscriber's station coöperative with said switching device for throwing it to the position to cause said signaling device to operate, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.

67. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impelled into the main line to the central station, means at the subscriber's station coöperative with said switching device for throwing it to the position to cause said signaling device to operate, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said main line circuit, said central station apparatus including instrumentalities coöperative with said auxiliary apparatus switching devices for setting and resetting the same, said auxiliary apparatus also including means controlled at the central station for locking out the subscriber's station.

68. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of

- energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, means coöperative with the respective station's switching device for disconnecting, from the main line circuit, the stations beyond during the time the respective station's signaling apparatus is transmitting signals, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
69. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, means at the subscriber's station coöperative with said switching device for throwing it to the position to cause said signaling device to operate, means coöperative with the respective station's switching device for disconnecting, from the main line circuit, the stations beyond during the time the respective station's signaling apparatus is transmitting signals, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
70. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, means at the subscriber's station coöperative with said switching device for throwing it to the position to cause said signaling device to operate, means controllable at the central station and coöperative with the switching device of the respective subscribers' stations for resetting the apparatus of the subscribers' stations, an auxiliary apparatus at each subscriber's station, said auxiliary apparatus being connected in said main line circuit and including a telephone set, one terminal of which is grounded, and the other terminal adapted to be connected operatively with the main line circuit, said auxiliary apparatus also including switching devices for operatively connecting said telephone set with the main line circuit, said central station apparatus including instrumentalities coöperative with said auxiliary apparatus switching devices for setting and resetting the same.
71. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, means at the subscriber's station coöperative with said switching device for throwing it to the position to cause said signaling device to operate, means controllable at the central station and coöperative with the switching device of the respective subscribers' stations for resetting the apparatus of the subscribers' stations, an auxiliary apparatus at each subscriber's station,

said auxiliary apparatus being connected in said main line circuit and including a telephone set, one terminal of which is grounded, and the other terminal adapted to be 5 connected with the main line circuit, said auxiliary apparatus also including switching devices for operatively connecting said telephone set with the main line circuit, said central station apparatus including instrumentalities coöperative with said auxiliary apparatus switching devices for setting and 10 resetting the same, said auxiliary apparatus also including means controlled at the central station for locking out the subscriber's 15 station.

72. In a system of the class described, a central station, two distinct sets of main line circuits emanating from the central station, a plurality of subscribers' stations connected in each main line circuit, an interchanging station into which the terminal ends of said main line circuits extend, main line sources of energy at said interchanging station for the respective main line circuits, 20 switching and bridging instrumentalities at the interchanging station responsive to current impulses from either main line circuit and for bridging over the terminal connections of the main line circuits, instrumentalities at the central station for sending out current impulses over the main line circuits to operate the interchanging station apparatus, and signal sending mechanism at the subscriber's station, and signal receiving 25 mechanism at the central station, substantially as shown and described.

73. In a system of the class described, a central station, two distinct sets of main line circuits emanating from the central station, a plurality of subscribers' stations connected in each main line circuit, an interchanging station into which the terminal ends of said main line circuits extend, main line sources of energy at said interchanging 40 station for the respective main line circuits, switching and bridging instrumentalities at the interchanging station responsive to current impulses from either main line circuit and for bridging over the 45 terminal connections of the main line circuits, instrumentalities at the central station for sending out current impulses over the main line circuits to operate the interchanging station apparatus, signal sending mechanism at the subscriber's station, signal receiving mechanism at the central station, and an auxiliary apparatus at each subscriber's station also connected in the main line circuit, said auxiliary apparatus including instrumentalities coöperative with devices at the central station for line testing purposes, and devices at the central station coöperative with the 50 same.

74. In a system of the class described, a central station, two distinct sets of main line circuits emanating from the central station, a plurality of subscribers' stations connected in each main line circuit, an interchang- 55

ing station into which the terminal ends of said main line circuits extend, main line sources of energy at said interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station apparatus, signal sending mechanism at the subscriber's station, signal receiving mechanism at the central station, said signal 60 sending mechanism of the subscribers' stations including automatic alarm devices for transmitting alarm signals to the central station, and mechanism at the central station for resetting the signal sending apparatus of the subscribers' stations upon completion of the signaling act.

75. In a system of the class described, a central station, two distinct sets of main line circuits emanating from the central station, a plurality of subscribers' stations connected in each main line circuit, an interchanging station into which the terminal ends of said main line circuits extend, main line sources of energy at each interchanging 70 station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station apparatus, signal sending mechanism at the subscriber's station, signal receiving mechanism at the central station, and an auxiliary apparatus at each subscriber's station also connected in the main line circuit, said auxiliary apparatus including instrumentalities coöperative with devices at the central station for line testing purposes, and devices at the central station coöperative with the 75 same.

76. In a system of the class described, a central station, two distinct sets of main line circuits emanating from the central station, a plurality of subscribers' stations connected on each main line circuit, an interchanging station into which the terminal ends of said main line circuits extend, main line sources of energy at the interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits 100

to operate the interchanging station, signal sending mechanism at the subscriber's station, signal receiving mechanism at the central station, said signal sending mechanism of the subscribers' stations including automatic alarm devices for transmitting alarm signals to the central station, and an auxiliary apparatus at each subscriber's station also connected in the main line circuit, said auxiliary apparatus including instrumentalities coöperative with devices at the central station for line testing purposes, and devices at the central station coöperative with the same.

15 77. In a system of the class described, a central station, two distinct sets of main line circuits emanating from the central station, a plurality of subscribers' stations connected on each main line circuit, an interchanging station into which the terminal ends of said main line circuits extend, main line sources of energy at said interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station, signal sending mechanism at the subscriber's station, signal receiving mechanism at the central station, said signal sending mechanism of the subscribers' stations including automatic alarm devices for transmitting alarm signals to the central station, mechanism at the central station for resetting the signal sending apparatus of the subscribers' stations upon completion of the signaling act, and an auxiliary apparatus at each subscriber's station also connected in the main line circuit, said auxiliary apparatus including instrumentalities coöperative with devices at the central station for line testing purposes, and devices at the central station coöperative with the same.

15

50 78. In a system of the class described, a central station, two distinct sets of main line circuits emanating from the central station, a plurality of subscribers' stations connected in each main line circuit, an interchanging station into which the terminal ends of said main line circuits extend, main line 55 sources of energy at each interchanging station for the respective main line circuits, switching and bridging instrumentalities at the interchanging station responsive to current impulses from either main line circuit and for bridging over the terminal connections of the main line circuits, instrumentalities over the main line circuits to operate the interchanging station apparatus, signal sending mechanism at the subscriber's station, signal receiving mechanism

65

at the central station, an auxiliary apparatus at each subscriber's station also connected in the main line circuit, said auxiliary apparatus including instrumentalities co-operative with devices at the central station 70 for line testing purposes, and also including a telephone set, one terminal of which is grounded, and the other terminal of which is adapted for being connected with the main line circuit, said auxiliary apparatus 75 also including mechanism controllable at the central station for effecting the operative connection of the telephone set of the subscriber's station with the main line, said auxiliary apparatus also including instrumentalities for locking out the auxiliary apparatus of a station. 80

79. In a system of the class described, a central station, two distinct sets of main line circuits emanating from the central station, a plurality of subscribers' stations connected in each main line circuit, an interchanging station into which the terminal ends of said main line circuits extend, main line sources of energy at the interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station, signal sending mechanism at the subscriber's station, signal receiving mechanism at the central station, said signal sending mechanism of the subscribers' stations including automatic alarm devices for transmitting alarm signals to the central station, an auxiliary apparatus at each subscriber's station also connected in the main line circuit, said auxiliary apparatus including instrumentalities coöperative with devices at the central station for line testing purposes, and also including a telephone set, one terminal of which is grounded, and the other terminal of which is adapted to be connected with the main line circuit, said auxiliary apparatus also including mechanism controllable at the central station for effecting the operative connection of the telephone set of the subscriber's station with the main line, said auxiliary apparatus also including instrumentalities for locking out the telephone set of a station. 115 120

80. In a system of the class described, a central station, two distinct sets of main line circuits emanating from the central station, a plurality of subscribers' stations connected on each main line circuit, an interchanging station into which the terminal ends of said main line circuit extend, main line sources of energy at said interchanging station for the respective main line circuits, switching and bridging instrumentalities at 130

the interchanging station responsive to current impulses from either main line circuit and for bridging over the terminal connections of the main line circuits, instrumentalities at the central station for sending out current impulses over the main line circuits to operate the interchanging station, signal sending mechanism at the subscriber's station, signal receiving mechanism at the central station, said signal sending mechanism of the subscribers' stations including automatic alarm devices for transmitting alarm signals to the central station, mechanism at the central station for resetting the signal sending apparatus of the subscribers' stations upon completion of the signaling act, an auxiliary apparatus at each subscriber's station also connected in the main line circuit, said auxiliary apparatus including instrumentalities cooperative with devices at the central station for line testing purposes, and also including a telephone set, one terminal of which is grounded, and the other terminal of which is adapted to be connected with the main line circuit, said auxiliary apparatus also including mechanism controllable at the central station for effecting the operative connection of the telephone set of the subscriber's station with the main line, said auxiliary apparatus also including instrumentalities for "locking out" the station.

81. In a system of the class described, a central station, two distinct sets of main line circuits emanating from the central station, a plurality of subscribers' stations connected in each main line circuit, an interchanging station into which the terminal ends of said main line circuits extend, main line sources of energy at each interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuit to operate the interchanging station apparatus, signal sending mechanism at the subscriber's station, signal receiving mechanism at the central station, an auxiliary apparatus at each subscriber's station also connected in the main line circuit, said auxiliary apparatus including instrumentalities cooperative with devices at the central station for line testing purposes, devices at the central station cooperative with the same, said auxiliary apparatus also including auxiliary main line terminal batteries, a switch for controlling the connection of said batteries with the main line circuit, and a second switching device for controlling the terminal connections of the subscribers' stations with the main line circuit, said

switches being operable by current impulses from the central station whereby any subscriber's station may be made a terminal station at the will of the central operator.

82. In a system of the class described, a central station, two distinct sets of main line circuits emanating from the central station, a plurality of subscribers' stations connected in each main line circuit, an interchanging station into which the terminal ends of said main line circuits extend, main line sources of energy at the interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station, signal sending mechanism at the subscriber's station, signal receiving mechanism at the central station, said signal sending mechanism of the subscribers' stations including automatic alarm devices for transmitting alarm signals to the central station, an auxiliary apparatus at each subscriber's station also connected in the main line circuit, said auxiliary apparatus including instrumentalities cooperative with devices at the central station for line testing purposes, and devices at the central station cooperative with the same, said auxiliary apparatus also including auxiliary main line terminal batteries, a switch for controlling the connection of said batteries with the main line circuit, and a second switching device for controlling the terminal connections of the subscribers' stations with the main line circuit, said switches being operable by current impulses from the central station whereby any subscriber's station may be made a terminal station, at the will of the central station operator.

83. In a system of the class described, a central station, two distinct sets of main line circuits emanating from the central station, a plurality of subscribers' stations connected in each main line circuit, an interchanging station into which the terminal ends of said main line circuits extend, main line sources of energy at said interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station, a signal sending mechanism at the subscriber's station, signal receiving mechanism at the central station, 125

said signal sending mechanism of the subscribers' stations including automatic alarm devices for transmitting alarm signals to the central station, mechanism at the central station for resetting the signal sending apparatus of the subscriber's station upon completion of the signaling act, an auxiliary apparatus at each subscriber's station also connected in the main line circuit, said auxiliary apparatus being connected to the signal sending mechanism of the subscriber's station and to the central station mechanism.

- 10 ilary apparatus including instrumentalities coöperative with devices at the central station for line testing purposes, devices at the central station coöperative with the same, said auxiliary apparatus also including auxiliary main line terminal batteries, a switch for controlling the connection of said batteries with the main line circuit, and a second switching device for controlling the terminal connections of the subscribers' stations with the main line circuit, said switches being operable by current impulses from the central station whereby any subscriber's station may be made a terminal station, at the will of the central station operator.

84. In a system of the class described, a central station, two distinct sets of main line circuits emanating from the central station, a plurality of subscribers' stations connected in each main line circuit, an interchanging station into which the terminal ends of said main line circuits extend, main line sources of energy at each interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station, apparatus, signal sending mechanism at the subscriber's station, signal receiving mechanism at the central station, an auxiliary apparatus at each subscriber's station also connected in the main line circuit, said auxiliary apparatus also including instrumentalities co-operative with devices at the central station for line testing purposes, devices at the central station co-operative with the same, and also including a telephone set, one terminal of which is grounded, and the other terminal of which is adapted to be connected with the main line circuit, said auxiliary apparatus also including mechanism controllable at the central station for effecting the operative connection of the telephone set of the subscriber's station with the main line, said auxiliary apparatus also including instrumentalities for locking out the auxiliary apparatus of a station, said auxiliary apparatus also including auxiliary main line batteries, a switch for controlling the connection of said

batteries with the main line circuit, and a second switching device for controlling the terminal connections of the subscribers' stations with the main line circuit, said switches being operable by current impulses from the central station whereby any subscriber's station may be made a terminal station, at the will of the central operator. 70

85. In a system of the class described, a central station, two distinct sets of main line circuits emanating from the central station, a plurality of subscribers' stations connected in each main line circuit, an interchanging station into which the terminal ends of said main line circuits extend, main line sources of energy at the interchanging station for the respective main line circuits, switching and bridging instrumentalities at the interchanging station, responsive to current impulses from either main line circuit and for bridging over the terminal connections of the main line circuits, instrumentalities at the central station for sending out current impulses over the main line circuits to operate the interchanging station apparatus, signal sending mechanism at the subscriber's station, signal receiving mechanism at the central station, said signal sending mechanism of the subscribers' stations including automatic alarm devices for transmitting alarm signals to the central station, an auxiliary apparatus at each subscriber's station also connected in the main line circuit, said auxiliary apparatus including instrumentalities coöperative with devices at the central station for line testing purposes, and also including a telephone set, one terminal of which is grounded, and the other terminal of which is adapted to be connected with the main line circuit, said auxiliary apparatus also including mechanism controllable at the central station for effecting the operative connection of the telephone set of the subscriber's station with the main line, said auxiliary apparatus also including instrumentalities for locking out the auxiliary apparatus of a station, said auxiliary apparatus also including auxiliary main line terminal batteries, a switch for controlling the connection of said batteries with the main line circuit, and a second switching device for controlling the terminal connections of the subscribers' stations with the main line circuit, said switches being operable by current impulses from the central station whereby any subscriber's station may be made a terminal station, at the will of the central station operator. 75 80 85 90 95 100 105 110 115 120

86. In a system of the class described, a central station, two distinct sets of main line circuits emanating from the central station, a plurality of subscribers' stations connected on each main line circuit, an interchanging station into which the terminal ends of said main line circuit extend, main line sources 130

of energy at said interchanging station for the respective main line circuits, switching and bridging instrumentalities at the interchanging station responsive to current impulses from either main line circuit and for bridging over the terminal connections of the main line circuits, instrumentalities at the central station for sending out current impulses over the main line circuits to operate the interchanging station apparatus, signal sending mechanism at the subscriber's station, signal receiving mechanism at the central station, said signal sending mechanism of the subscribers' stations including automatic alarm devices for transmitting alarm signals to the central station, mechanism at the central station for resetting the signal sending apparatus of the subscribers' stations upon completion of the signaling act, an auxiliary apparatus at each subscriber's station also connected in the main line circuit, said auxiliary apparatus including instrumentalities coöperative with devices at the central station for line testing purposes, and also including a telephone set, one terminal of which is grounded, and the other terminal of which is adapted to be connected with the main line circuit, said auxiliary apparatus also including mechanism controllable at the central station for effecting the operative connection of the telephone set of the subscriber's station with the main line, said auxiliary apparatus also including instrumentalities for locking out the auxiliary apparatus of a station, said auxiliary apparatus also including auxiliary main line terminal batteries, a switch for controlling the connection of said batteries with the main line circuit, and a second switching device for controlling the terminal connections of the subscribers' stations with the main line circuit, said switches being operable by current impulses from the central station whereby any subscriber's station may be made a terminal station, at the will of the central station operator.

87. In a system of the class described, a central station; a plurality of sections of installations, each including a plurality of subscribers' stations and a main line circuit connecting said subscribers' stations with the central station; central station apparatus for each section of installation; an interchanging station in which the terminal ends of the main line circuits of two sections of installation terminate; instrumentalities at the interchanging station, operatively controlled from the central station for bridging over the terminal ends of the two main line circuits to form a through connection between the same at the interchanging station; means at the interchanging station and controlled from the central station for resetting the interchanging station apparatus; said subscriber's station apparatus and said central

station apparatus each including a telephone set, one terminal of which is grounded and the other terminal is adapted to be connected to the main line circuit; each subscriber's station apparatus including switching devices operative by current impulses entering the subscriber's station from the central station for selectively connecting a subscriber's station for telegraphic communication; means at the subscriber's station and controlled from the central station for locking out the subscribers' stations between those set for telephonic communication; and means controlled at the central station for resetting the subscribers' stations apparatus. 70 75 80

88. In a system of the class described, a central station; a plurality of sections of installations, each including a plurality of subscribers' stations and a main line circuit connecting said subscribers' stations with the central station; central station apparatus for each section of installation; an interchanging station in which the terminal ends of the main line circuits of two sections of installation terminate; instrumentalities at the interchanging station, operatively controlled from the central station for bridging over the terminal ends of the two main line circuits to form a through connection between the same at the interchanging station; means at the interchanging station and controlled from the central station for resetting the interchanging station apparatus, said subscriber's station apparatus and said central station apparatus each including a telephone set, one terminal of which is grounded, and the other terminal of which is adapted to be connected to the main line circuit; each subscriber's station apparatus including switching devices operative by current impulses entering the subscriber's station from the central station for selectively connecting a subscriber's station for telegraphic communication; means at the subscriber's station and controlled from the central station for locking out the subscribers' stations between those set for telephonic communication; means controlled at the central station for resetting the subscribers' stations apparatus, each of said subscribers' stations including alarm signal sending apparatus connected in the main line circuit for sending telegraphic signaling impulses to the central station; the central station apparatus including devices for receiving and indicating said telegraphic signal impulses; and means for resetting said signal sending apparatus of the subscribers' stations. 90 95 100 105 110 115 120 125 130

89. In a system of the character stated, a central station, a plurality of sets of installations including main line circuits emanating from the central station, a plurality of subscribers' stations in said main line circuits, an interchanging station in which the terminal ends of two sections of installation

- terminate, switching and bridging devices at said interchanging station and controllable at the central station by means of which the terminal ends of two sections of 5 installation may be bridged over to form a through line at the interchanging station from one section to the other, each of said subscribers' stations including fire and burglar alarm signaling apparatus and an auxiliary apparatus and a line terminal connection changing switch connecting the line terminals of the apparatuses of the subscribers' stations, said auxiliary apparatus including mechanism whereby the fire and 10 burglar alarm apparatus may be operatively located at all times on the side adjacent to the central station whereby the fire and burglar alarm signals will be directly transmitted to the central station, said fire and burglar alarm apparatus including means for cutting out the line connection of the auxiliary apparatus and the stations beyond that station whose signal is being received at 15 the central station, and signal receiving apparatus at the central station.
90. In a system of the class described, a central station, a main line circuit emanating from the central station, a plurality of subscribers' stations in said main line circuit, 20 each of said subscribers' stations being provided with two distinct sets of apparatus; the first of said sets of apparatus including instrumentalities for sending alarm signaling impulses into the main line circuit, signal receiving apparatus at the central station for receiving said alarm signals, means for resetting said alarm signal sending apparatus, said alarm signal sending apparatus being designed to send out the signals 25 over the main line circuit toward the central station in one direction, auxiliary apparatus including a line terminal connection-changing switch for changing the line terminal connections that enter the subscriber's station so as 30 to maintain the alarm signal apparatus connected—for operative location between the auxiliary apparatus and the central station
- according as said subscriber's apparatus is connected in the installation for communication with the central station in one direction 50 or the other.
91. In a system of the character stated, two distinct sets of installation each including a main line circuit, a central station from which said circuits emanate, a plurality of subscribers' stations in each circuit, an interchanging station into which the terminal ends of said main line circuits run, switching and bridging instrumentalities in 55 said interchanging station for bridging over the terminal ends of the two main line circuits to provide a through line through the interchanging station, means at the central station for controlling the instrumentalities, each subscriber's station being provided with 60 two distinct sets of apparatus the first of said sets of apparatus including alarm signal sending devices for transmitting alarm signaling impulses into the main line circuit toward the central station in one geographical direction, said auxiliary apparatus including mechanism controlled at the central station for line testing and telephoning purposes, said auxiliary apparatus including auxiliary main line batteries and a switching 65 device for bringing the same into circuit, said auxiliary device also including a line terminal switch coöperative with the line terminal connections of the subscriber's station apparatuses and operatively controlled 70 at the central station for changing the line terminal connections to locate the alarm signal mechanism always on the side of the station adjacent to the central station whereby the telegraphic impulses may be transmitted into the main line circuit in the proper direction accordingly as the station is set for operation over one section of the installation or over the other section of the same.

OTTO ASMUSSEN.
